BOBBIN WINDING MACHINE

Harry T. O'Neill, Jr., New Bedford, Mass., assignor to Continental Elastic Corporation, a corporation of Massachusetts

Application June 28, 1950, Serial No. 170,864

53 Claims. (Cl. 242—35.5)

1

This invention relates to automatic winding machines of the type for simultaneously winding a plurality of substantially identical spools or bobbins of thread and though of general application, is illustratively shown as applied to the winding of bobbins of conventional type having driving teeth on the periphery of the outer face of a flange end thereof, for use on automatic braiding machines.

As conducive to an understanding of the invention, it is to be noted that as a relatively large number of bobbins of thread are required for each braid that is formed on the conventional automatic braiding machine, unless such bobbins can be wound with a minimum of expense, the cost of the finished braided product will be correspondingly high.

In a winding machine of the type with which the present invention is concerned and which has a plurality of stations for winding a corresponding number of bobbins, the sequence of operation includes the feeding of empty bobbins into alignment and in gripping engagement with driving spindle shafts at said stations, the gripping of the end of thread so that it will not slip off said bobbin as the latter begins rotating, the guiding of the thread as it is wound on the bobbin barrel to provide for an even lay, the stopping of the winding spindle shafts when a predetermined number of turns of thread has been wound on the bobbins, the release of the wound bobbins from the driving spindle shafts, the severing of the thread between the wound bobbin and the thread supply roll, and the discharge of such wound bobbins from the machine.

Due to manufacturing tolerances in the bobbins and the bobbin winding mechanism and to variations in the thickness of thread being wound, material variations occur in the length of thread upon bobbins successively wound in a predetermined large number of layers and turns, or upon a plurality of bobbins when wound simultaneously. Thus, for instance, a bobbin having thread with thickened thread portions, or having its thread under lesser tension will build up its layers faster than other bobbins.

Because of such material variation in the length of thread wound upon the bobbins to be used on the braiding machine, all of the bobbins are generally replaced when the bobbin with the shortest length of thread is exhausted, which entails considerable waste of the unused lengths of thread on the other bobbins.

Where the layers of thread are not distributed evenly over the entire length of the bobbin barrel

2

as for instance, when the thread guide does not move through the entire length of the bobbin barrel, the resultant collapse of wound thread into the unfilled ends will develop soft spots at such ends. As a result, when used on the braiding machine, the thread, which is braided under tension, may fall into such soft spot and snag, with resultant breakage which would require stoppage of the machine for time-consuming retying of such thread ends, thereby reducing the output and requiring supervisory personnel, with consequent high cost of the finished product. In addition, such frequent tying of thread will result in knots and therefor an inferior product.

Such soft spots are also caused when the inside end of the thread, which is secured to the flange end of the bobbin at the beginning of the winding cycle, is not released, and when such end extends tautly at an oblique angle downward from the periphery of the bobbin flange to the barrel portion thereof, layers of thread will wind in conical shape over such taut end and the gradual collapse under the pressure of the successive layers results in a soft spot with the disadvantages above set forth.

Such automatic machine is likely to jam with possibility of damage to its mechanism and, in any event, with the need for frequent stoppage and constant supervision in order to cut the thread in the event it should not automatically be severed between a bobbin that has been wound and its successor to be wound.

Where the automatic winding machine discharges the wound bobbins into an open container, the flange ends of the bobbins, which are generally dirty due to their use on the braiding machine, may contact the wound layers of thread on the other bobbins with resultant soiling which entails the need for supervisory inspection personnel and in addition, the waste or cost of discarding or cleaning such soiled bobbins.

Where, to prevent such soiling, attempts are made to deposit the wound bobbins upon successive rows of upright pins on pin boards, which are indexed row by row in timed relation with the operation of the winding machine, a large proportion of the bobbins may become disarranged, causing the flange ends thereof to rub against the thread on other bobbins with resultant soiling thereof, aside from the fact that such boards may be bulky.

Where control of the sequence of operations of an automatic bobbin winding machine is attempted by mechanical means, the many elaborate linkages, cams, levers and clutches required

to shift from one operation to another, and the relatively great rotating mass of the moving parts, is incompatible with high speed operation and in addition such mechanical linkages, cams, levers and clutches are a constant source of breakdown and failure, entailing frequent stoppage for adjustment and regulation, which adds materially to the cost of the finished product and despite all precautions, the required uniformity of thread length and wind is not accomplished.

It is, accordingly, among the objects of the invention to provide an automatic machine for simultaneously winding a plurality of substantially conventional bobbins at a high rate of speed with but little supervision, which machine includes no elaborate mechanical linkages or the like, is unlikely to become deranged and will wind all of the bobbins thereon in substantially uniform layers with substantially the same thread length on each bobbin and with substantially equal tension on all threads without likelihood of soft spots in the layers wound, and will dependably and reliably sever the thread after the bobbin has been wound and afford ready access for any needed maintenance or repair.

Another object is to provide a bobbin disposal mechanism for a winding machine of the above type which will reliably discharge and collect the wound bobbins without likelihood of contact of the flange end of one of said bobbins with thread wound on another.

Another object is to provide an electrical control system which is relatively compact, readily accessible for adjustment and not likely to become deranged, which, when once adjusted will accurately regulate the sequence of mechanical operations that will enable a predetermined number of turns and layers of thread to be wound without soft spots and will dependably sever the thread between the wound bobbin and its successor.

According to one feature of the invention means is provided to release the retained end of thread after a few layers are wound on the barrel of the bobbin so that the otherwise taut oblique end is released to enable successive layers of thread to fill the entire length of the bobbin barrel from the inner periphery of the flange thereof against which the end of the thread is retained.

In the illustrative embodiment herein shown, the driving head has two concentric, relatively movable rings rotatable with the associated driven spindle shaft, the outer ring being designed to engage the face of the driving tooth end of the bobbin, and the inner ring being designed to press the thread, which normally lies across the outer face of the flange of such bobbin in the spaces adjacent diametrically opposed driving teeth, against the gripping portion of such outer face of the bobbin flange which is encompassed by said teeth.

The faces of the rings normally are resiliently retained in substantially the same plane until the bobbin presser head moves the bobbin axially toward the driving head so that the driving teeth of the bobbin flange press against the outer ring which is in driving engagement with said teeth. This will cause the outer ring to move axially away from the inner ring, which latter will thereupon press the thread against the gripping portion of the bobbin.

The thread thus anchored to the bobbin head is automatically released after the first few turns have been wound, so that the oblique taut end that would lead to a soft spot is slackened. For this

purpose means is provided slightly to move the bobbin presser head away from the bobbin, and the outer ring is spring urged to follow the slightly receding presser head and release the clamped end of thread while maintaining the bobbin in driving position.

To effect the desired substantially uniform length of thread on each bobbin, automatic tension equalizing means, freely rotatable as a unit, and desirably an elongated roller, is interposed between the bobbins and the supply spools, frictionally to be driven by the span of threads extending between the conventional tension discs and the bobbins and thereby equalizing the linear speed of all the threads.

To maintain the frictional engagement of each thread with the tension equalizer, regardless of acceleration of one or more threads, a series of pivoted tension arms engage the respective threads between the bobbins and the tension equalizer.

Another feature is so to arrange the tension arms, that upon breaking of any thread the resilient means associated with said tension arm will pivot the latter upwardly to actuate a switch for stopping further rotation of the bobbins.

After the bobbins have been wound and while the driving spindle shafts are coasting to a stop, the upward movement of the roller ends of the tension arms is restrained to insure that the tension on the threads will be relaxed, and means are also provided to move the bobbin presser heads axially away from the driving head so that each of the wound bobbins may fall into an associated hopper. At such time, a new supply of empty bobbins is advanced to the winding position and concurrently indexed and as this occurs, the threads which extend from the wound bobbins deposited in the bobbin hopper will be reliably moved between associated pairs of scissor blades and then gripped by suitable means. The tension arms will now be released again to tension the threads, and the bobbins which now have been moved into axial alignment with the driving heads and bobbin presser heads and which have been previously indexed so that the threads against the faces of the associated driving heads lie in the spaces adjacent a diametrically opposed, vertically aligned pair of teeth on the bobbin flange, will be moved by the bobbin presser head against the driving head in the manner previously described. The scissor blades will then be actuated, dependably to sever the threads, and the next winding cycle will occur.

The wound bobbins which have been deposited in the hopper, are discharged therefrom, desirably after the end of the next winding cycle, and guided in substantially vertical position down a chute, the outlets of which are vertically aligned with longitudinal compartments in a suitable bobbin box. Means are provided to advance the vertically stacked rows of bobbins in said box in timed relation with the operation of the machine so that room will be provided in such longitudinal compartments to receive the successive bobbins.

In order to control the operations above described an electrical control system is provided whereby the operations will occur in proper timed sequence to insure that the wound bobbins will all be of the same length, wound with substantially the same tension and devoid of soft spots.

In the accompanying drawings in which are shown one or more of various possible embodiments of the several features of the invention,

Fig. 43 is a circuit diagram of the control system for the winding machine.

In order that the invention may be clearly understood, the substantially conventional bobbin used in the machine will first be described and thereafter the parts of the preferred specific embodiment shown will be described under appropriate titles.

Bobbin

(Figs. 15, 18 and 20)

The bobbin 63 used in the embodiment of the winding machine herein shown is a spool preferably having a tubular barrel 64 with flanges 65 and 66 at its opposite ends. As shown in Figs. 15, 18 and 20, the outer face of at least one of the flanges, illustratively flanges 65, has a plurality of driving teeth 71 desirably radially arranged on the periphery thereof, rising from the outer face of the flange 65. The driving teeth 71 define a gripping surface 72 coaxial with the bore 73 of said bobbin barrel and encompassed by said teeth. As shown in Fig. 18, the faces 74 of the driving teeth are substantially flat and desirably one side of each of said teeth has a flat wall 75 and the other side of each of said teeth has a curved wall 76 which extends to the inner end of the flat wall of an adjacent tooth.

Frame-work

(Figs. 1 and 2)

Although any suitable structure or frame-work may be used to mount the operating parts of the machine, the preferred embodiment herein illustratively shown in Figs. 1 and 2, desirably comprises a frame 51 which may be of open construction, preferably of cast iron or steel, having a plurality of legs 52 preferably affixed to the floor.

Securely mounted on spaced cross bars 53 longitudinally of the frame 51 and affixed at their ends on the horizontal portions 54 thereof is a substantially rectangular table which desirably comprises four angle irons 55, 56, 57 and 58 bolted together at their ends as at 61, the side angle bars 55 and 57 of said table being affixed to said cross bars 53 as at 62.

Bobbin spindle shafts and drive mechanism therefor

(Figs. 1, 2, 29 and 31)

A plurality of parallel spindle shafts are provided, illustratively four in number and designated by the numerals 81, 82, 83 and 84, each to rotate one bobbin 63 to wind thread thereon. As shown in Figs. 2 and 29, the spindle shafts extend forwardly, desirably in a common hori-

zontal plane, through the front wall 85 of a substantially rectangular gear box 86 mounted on the spaced cross bars 53 as shown in Fig. 2 adjacent the angle iron 55.

As shown in Fig. 31, the gear box 86 desirably has a removable top cover 87 with a window plate 91 therein. Desirably the gear box contains a pool of oil in which the gears may rotate with a minimum of friction.

To rotate the spindle shafts 81, 82, 83 and 84, 10 the mechanism, shown in Figs. 2, 29 and 31, desirably includes a motor 90 which may be mounted to rest on angle iron 58 and the adjacent cross bar 53.

The drive shaft 92 of motor 90 has pulleys 93 15 affixed thereto which are operatively connected as by means of belts 94 to pulleys 95 affixed on the drive shaft 96 which extends transversely of the gear box 86 through the end walls 97 and 98 thereof.

As shown in Fig. 29 a pair of spaced parallel upstanding walls 101 and 102 near the front and rear walls 85 and 103 respectively of said gear box are preferably cast integral therewith. A pair of bearing blocks 104 and 105 shown in Figs. 29 and 31 are affixed to the upper edge of wall 101 as by bolts 106 and rotatably mount the drive shaft 96 which extends through said bearings. Rotatably mounted in suitable bearing openings in walls 101 and 102 and extending through the front wall 85 of the gear box 86 are a pair of the spindle shafts 81 and 84 at right angles to drive shaft 96 and driven therefrom through a suitable transmission.

As shown in Figs. 29 and 31 such transmission desirably comprises a pair of helical gears 107 and 108 affixed on drive shaft 96 near the respective bearing blocks 104 and 105, said wall 101 having recesses 111 therein to accommodate the periphery of said helical gears. Helical gears 107 and 108 mesh respectively with corresponding helical gears 112 and 113 affixed on the adjacent ends of spindle shafts 81 and 84, respectively as shown in Fig. 29 to drive said spindle shafts.

Desirably, collars 114 and 115 are affixed on spindle shafts 81 and 84 respectively, adjacent the outer face 116 of upstanding wall 102; the helical gears 112 and 113 and the collars 114 and 115 preventing axial displacement of said spindle shafts 81 and 84 through the associated bearing openings in walls 101 and 102.

The second pair of spindle shafts 82 and 83 desirably lie in the same horizontal plane as spindle shafts 81 and 84 and also extend through the front wall 85 of the gear box 86. Spindle shafts 82 and 83 are rotatably mounted in suitable bearing openings in upstanding wall 102 and in a wall 117 also desirably formed integral with the gear box 86 and positioned between walls 101 and 102 and extending parallel thereto adjacent to wall 102.

To rotate spindle shafts 82 and 83, spur gears 118 and 119 are desirably affixed on spindle shafts 81 and 84 respectively, adjacent the inner face 121 of wall 102, said spur gears 118 and 119 meshing respectively with idler gears 122 and 123 rotatably mounted respectively on spaced parallel guide rods 124 and 125 which extend through walls 101, 117 and 102, being secured at each end as by nuts 126.

As can be seen from Fig. 29, the idler gears 122 and 123 are restrained from axial displacement on said guide rods 124 and 125 by their hubs 127 which are between the walls 102 and 117. Idler gears 122 and 123 mesh respectively

with spur gears 128 and 129 affixed respectively to spindle shafts 82 and 83 between walls 102 and 117 to rotate said spindle shafts.

With the construction thus described, it is apparent that all of the spindle shafts will rotate in the same direction and as the spur gears desirably have a ratio of one to one with respect to each other, the spindle shafts will all rotate at the same rate of speed.

In order that the spindle shafts may drive the bobbins 63 associated therewith, each of said spindle shafts, as shown in Fig. 15 has a driving head 131 mounted thereon and a bobbin presser head 132 axially spaced therefrom. These elements will now be described in detail.

Bobbin driving heads

(Figs. 15 and 17)

As shown in Figs. 15 and 17, the driving head 131 associated with each of the spindle shafts desirably comprises a sleeve 132' encompassing the free end 133 of the spindle shafts (spindle shaft 81 being illustratively shown) and affixed thereto as by a set screw 134 through flange 135 at the end of the sleeve 132'.

The end 133 of the spindle shaft has a substantially cylindrical bore 136 therein, internally threaded as at 137 at its extremity and having a stud 138 threaded therein. Stud 138 is desirably of enlarged diameter at its outer end as at 139 forming a shoulder 142 which seats against the end of the spindle shaft and the front of the enlarged portion 139 of the stud has a shoulder 148 which forms an annular seat on which is positioned a ring 149 of resilient material, preferably rubber or similar substance. The enlarged end 139 of the stud has a cylindrical recess 143 therein in communication with an axial bore 144 which extends through the stud and a centering pin 145 is slidably mounted in said bore 144 with one end of said pin 145 extending into the bore 136 of said spindle shaft 81 and with the other end of said pin 145 extending into said recess 143. The centering pin 145 has an enlarged head portion 146 affixed at the end thereof in said recess 143, said head portion having a conical nose 147. In order to prevent the inner end of the centering pin 145 from moving through the bore 144 of the stud 138, a cross or stop pin 151 extends transversely through said centering pin. The centering pin is normally retained with its head portion 146 in outermost position, by means of a coil spring 152 positioned in the bore 136 of the spindle shaft 81 and compressed between the end wall 153 of said bore and the cross pin 151.

Encompassing sleeve 132' is a sleeve 152' having an internal annular flange 153' which rides on the enlarged portion 139 of said stud 138, with the rear end of sleeve 152' riding on the sleeve 132' as is clearly shown in Figs. 15 and 17.

The sleeve 152' desirably has an annular radial flange 155 at the front thereof coaxial with and encompassing an annular flange 156 on the enlarged portion 139 of stud 138. Desirably the periphery of annular flange 155 has an outstanding rim 157 preferably formed integral therewith, said rim 157 and said flange 155 defining a cavity in which a resilient ring 158 preferably of rubber or like material is positioned, said ring 158 being coaxial with and encompassing ring 149.

Means are provided normally to urge said outer sleeve 152' to its outermost position as shown in Fig. 17 in which position the front face of flange 153' will abut against the rear face

of flange 156 with the outer faces of rings 149 and 158 lying in substantially the same vertical plane as shown in Fig. 17. To this end a coil spring 161 is provided encompassing the enlarged portion 139 of the stud 138 and compressed between the end of inner sleeve 132' and the rear face of flange 153'.

In order to spline the outer sleeve 152' to the inner sleeve 132' which is rigidly affixed to the spindle shaft 81 so that rotary movement may be imparted to said outer sleeve, yet permitting sliding movement thereof, the outer sleeve 152' is desirably provided with longitudinal bores 163 therein, into which extend the ends of longitudinally extending pins 164 rigidly affixed at their rear ends to the flange 135 of inner sleeve 132'.

Bobbin presser head

(Figs. 2, 8, 10, 13, 14 and 15)

Associated with each of the driving heads 131 is the bobbin presser head 132 which, as shown in Fig. 15 desirably comprises a rod 166 having an internally threaded recess 167 at one end in which is positioned a holder 168. This holder desirably comprises a socket 169 having a stem 171 preferably formed integral therewith, which stem is externally threaded so that it may be screwed into the recess 167 of rod 166. Positioned in said socket 169 is a substantially conical head 172 having an axial stem 173 on the rear face 174 thereof, which extends through an axial bore 175 in said holder. The head is retained in said holder by means of a snap ring 176 coacting with an annular groove 177 in the rear end of said stem 173 which extends through the bore 175 of said holder 168. In order to provide for substantially frictionless rotation of said head 172, in said socket 169, a plurality of ball bearings 176' are provided positioned in a race or ball seats 177' in the opposed adjacent faces of said head and said holder.

As shown in Figs. 13, 14 and 15, each of the rods 166 and the associated head 172 thereof is axially aligned with one of the spindle shafts and each of the rods 166 is slidably mounted in an associated bearing block 181 affixed to the table of the machine.

As shown in Figs. 2, 13 and 14, in order to support the bearing blocks 181, a pair of spaced parallel supporting bars 182 and 183 (Fig. 2) extend forwardly from the front angle iron 56 being affixed thereto by means of screws 184 as shown in Figs. 13 and 14. Affixed on the ends of each of said supporting bars 182 and 183 as by screws 185, are blocks 186 and 187, the outer ends 188 of which extend slightly beyond the ends 189 of said supporting bars. The inner ends of said blocks desirably have a notch 191 on which is affixed as by screws 192 (Fig. 10) the ends of a longitudinal cross bar 193. Affixed to said cross bar 193 as by screws 194 are the bases 195 of said bearing blocks 181, said bases being affixed to the cross bar 193 so that the bearing block 181 extends at right angles thereto with the bore 196 of each of said bearing blocks axially aligned with an associated spindle shaft as shown in Fig. 15.

Means are desirably provided to prevent rotation of rod 166 in its associated bearing block 181, such as by a longitudinal groove 197 therealong which accommodates a pin 198 extending through the wall 199 of the bearing block 181.

Means are provided normally to urge the rod 166 to its outermost position in its bearing block 75

181 so that the head 172 thereon may be resiliently urged against the adjacent flange end 66 of a bobbin 63 to move the latter against the driving head 131. Thus, as shown in Fig. 15 the apex 14 of the driving teeth 71 will press against the outer ring 158, moving the sleeve 152' carrying the latter axially inward against the compressed coil spring 161 until the gripping surface 72 of the bobbin flange 65 abuts against inner ring 149. To this end, as shown in Fig. 15, the rod 166 has a reduced stem 203 which extends through an opening 204 in the end wall 205 of the bearing block 181. A coil spring 206 encompassing said reduced stem 203 is compressed between the end wall 205 of said bearing block 181 and the shoulder 207 formed by said reduced stem end normally to urge the rod out of the bore 196. In order to limit the outward movement of rod 166, a collar 208 is mounted on the protruding extremity thereof being retained thereon by means of a cross pin 209.

A bobbin conveyor assembly is provided in order to re-charge the winding heads with empty bobbins and this will now be described.

Bobbin conveyor

(Figs. 2, 4, 9, 11, 12, 13, and 14)

The bobbin conveyor desirably comprises a carriage 213 which, as shown in Fig. 9 has a pair of parallel bars 214 and 215 retained in spaced relation by means of interposed transverse rods 216 and 217 affixed thereto at their ends. Means are desirably provided slidably to mount the carriage so that it may be advanced longitudinally of the machine to feed bobbins from a bobbin magazine 221 shown in Fig. 1 to the driving spindle shafts 81, 82, 83 and 84.

To this end, a pair of spaced parallel tracks 222 and 223 may be mounted respectively on angle bar 56 and the cross bar 53 adjacent thereto to extend longitudinally thereof, said tracks being spaced from their associated supports by means of spacer collars 224 as shown in Fig. 11.

Illustratively, one of the bars 214 of the carriage has spaced lateral studs 225 on the outer face thereof as shown in Fig. 2 and bar 215 has a longitudinal shoulder portion 226 which rides on the inner edge of track 223.

As shown in Figs. 2, 9, 10 and 13 there is provided on said carriage 213 removably to carry a plurality of bobbins 63, means desirably comprising a substantially rectangular cradle 228, between bars 214 and 215 of carriage 213 and preferably of suitable cast metal. The cradle has spaced side walls 229 and 231 and end walls 232 and 233. The upper edges of the side walls 229 and 231 of the cradle 228 have a plurality of transversely aligned pairs of substantially V-shaped notches 234 therein, each adapted to receive the barrel 64 of a bobbin 63, the side walls 229 and 231 being so spaced that the flange ends 65, 66 of a bobbin 63 will straddle such walls as is clearly shown in Fig. 13.

As shown in Figs. 11 and 12, the cradle 228 normally rests on the transverse rods 216 and 217 which connect the bars 214 and 215 of the carriage 213, said rods being positioned respectively in transversely aligned pairs of substantially triangular notches 236 and 237 respectively in the lower edges of the side walls 229 and 231 of the cradle. Each notch 236 and 237 has a vertical edge 238 and an oblique cam edge 239 along which the rods 216 and 217 may ride in the manner hereinafter set forth.

11

As shown in Fig. 9, the cradle 228 is retained against lateral displacement from any selected position between the sides of the carriage 213 by means of collars 241 adjustably fixed to rods 216 and 217 by set screws 242.

Bobbin magazine

(Figs. 1, 4, 11, 22 and 23)

As shown in Figs. 1, 4 and 11, the bobbin magazine 221 desirably comprises a plurality of upstanding racks 244, each accommodating a plurality of stacked bobbins 63.

As shown in Figs. 1 and 22, each of the racks 244 comprises a pair of spaced upstanding channel members 245 and 246 having the side walls thereof directed toward each other, each channel to straddle the heads of the corresponding ends of the bobbins retained in the rack. As shown in Figs. 22 and 23, the bottom portions of the transversely aligned pairs of channel members 245, 246 are rigidly affixed to side plates 247 and 248 respectively as by welding. In order to retain said plates 247 and 248 in spaced parallel relation, with the channel members extending upwardly therefrom in transversely aligned pairs, the threaded reduced end of a hollow bolt 253 extends through a corresponding opening 251, 252, the head 254 of said bolt being securely clamped against the inner face of the corresponding plate as by nut 255 threaded on the end of such bolt. Extending through each of the transversely aligned pairs of hollow bolts 253 is a supporting rod 258, said rods being securely retained in position by means of set screws 257 which extend through the corresponding bolt heads 254 in engagement with said rod 256.

In order to mount the magazine 221 thus far described, as shown in Figs. 22 and 23, a pair of spaced upstanding posts 258 and 259 are affixed at their lower ends to each of the tracks 222 and 223 respectively. Slidably mounted on each of said posts is a clamp member 262 which, as shown in Fig. 22, may comprise a short rod having a vertical bore 263 therein through which its associated post passes, said clamp member 262 extending at right angles to said post and being retained in any selected position thereon by means of a set screw 264. The free end of each of said clamp members has a transverse bore 265 into which one of the ends of the corresponding supporting rod 256 extends, said rod being retained by means of a set screw 266.

With the construction thus described, the lower ends of each of the racks 244 of the magazine 221 will extend transversely across the tracks 222, 223 and may be spaced thereabov any selected distance to permit the cradle 228 on the carriage to pass therebeneath in the manner hereinafter to be described.

As shown in Figs. 4, 11 and 22, a horizontal slide plate 271 may extend beneath the lower ends of each of the racks 244 in order to prevent discharge of bobbins 63 when the racks are loaded. The plate 271 may have a plurality of transverse openings 272 normally positioned between the bottoms of consecutive racks 244 when the latter are closed as shown in Fig. 4 by the straps 273 between openings 272 of plate 271.

Each of the transverse openings 272 has a substantially L-shaped bracket 274 associated therewith, with a laterally extending mounting flange 275 affixed to the plate 271 from which rises the vertical leg 276, from the upper end of which horizontal ledge 278 extends over the cor-

12

responding opening 272. Ledge 278 is slightly inclined upwardly at such height that its free end 279 may pass between the barrel 64 of the lowermost bobbin in the associated rack and the one immediately above as shown in Figs. 4 and 11.

Means are provided slidably to mount the closure plate 271 so that it may be moved from its normal position in which the straps 273 thereof lie beneath the racks 244 respectively as shown in Fig. 4 to close the latter, to the position shown in Fig. 11 in which the transverse openings 272 register with the associated racks 244 to permit discharge of a bobbin therefrom.

To this end as shown in Figs. 22 and 23, plate 271 is mounted at its opposite longitudinal edge 286 in slots 285 in the ends 284 of guide blocks 281. The latter are slidably mounted on transversely aligned pairs of posts 258, 259 which extend through vertical bores 282 in blocks 281, the latter being retained in position on said posts by set screws 283.

To reciprocate closure plate 271 as shown in Figs. 4 and 22, it has a transverse bar 285' rigid therewith at one end thereof with an upstanding hook 287 thereon to which is secured one end of a tensed coil spring 288, the other end of which is secured to a stud 289 extending laterally outward from side walls 247 and 248 respectively.

Means are desirably provided to move the carriage 213 longitudinally along its tracks 222, 223 to position the cradle 228 beneath the bobbin magazine 221 and to actuate the closure plate 271 of the latter to deposit bobbins 63 in the notches 234 of said cradle 228, and also to move said carriage 213 and the cradle 228 to the spindle shafts to present the empty bobbins 63 for interposition between the associated pairs of driving heads 131 and bobbin presser heads 132.

To this end, a carriage drive mechanism is provided which will now be described.

Carriage drive mechanism

(Figs. 2, 9, 10, 26 and 30)

As shown in Fig. 2, this drive mechanism desirably comprises a motor 290 mounted on suitable cross bars 292 affixed to angle iron 57 and to a supporting bar 293 extending parallel thereto and affixed at its ends as at 294 and 295 to rear angle iron 58 and cross bar 53.

The shaft 296 of motor 290 may be connected through a torque limit switch 297 (which opens the motor circuit when excessive torque is applied and which as it is conventional in construction will not be described) to a reduction gear housing 298 mounted on a pair of cross bars 299 affixed to angle iron 57 and cross bar 293 respectively.

The gears in reduction gear housing 298 drive a shaft 301 which desirably extends from such reduction gear housing at right angles to said shaft 296. The end of shaft 301 is operatively connected by means of a coupling 302 to a shaft 303 which, as shown in Figs. 26 and 30 is rotatably mounted in bearings 304 and 305 in a housing 306 which, as shown in Figs. 2, 26 and 30 is affixed by laterally extending legs 307, 308 and 309 to the frame of the machine.

As shown in Figs. 26 and 30, a worm 313 on shaft 303 meshes with a horizontal worm gear 314 rigidly mounted on vertical shaft 315, rotatably mounted in said housing 306. Rigidly affixed to said shaft as shown in Figs. 26 and 30, is a crank arm 316, the free end which will rotate through an angle of 360 degrees with the rotation of said vertical shaft 315. The free end

317 of the crank arm 316 has a depending stud 321 thereon which rides in a longitudinal slot 322 in a main operating lever 323 which, as shown in Figs. 2 and 26, is pivotally mounted at one end as at 324 to a cross bar 325 extending between side angle bars 55 and 57.

As shown in Figs. 9 and 26 the main operating lever 323 desirably comprises two legs 327 and 328 extending parallel to each other and defining the slot 322 therebetween. The rear end of leg 328 (Fig. 26) has an enlarged portion 331 on which is mounted a switch 322, the latter having a plunger 333 extending laterally of said leg. The front end of leg 328 (Fig. 9) has a laterally extending portion 334 desirably with an arcuate notch 335 therein on the inner edge thereof which forms one of the ends of slot 322, and an upstanding block 336 is rigidly mounted on lateral portion 334.

Leg 327 is pivotally mounted at its rear end (Fig. 26) as at 337 on the enlarged portion 331 of leg 328 and desirably has an upstanding stud 339 thereon adapted to contact the roller 343 on plunger 333 to actuate switch 332 when legs 327 and 328 are parallel to each other as shown in Fig. 26.

Means are provided releasably to retain legs 327 and 328 in parallel relation. To this end, as shown in Fig. 9 the free end of leg 327 has an enlarged portion 344 on which the lateral portion 334 of leg 328 may seat. The enlarged portion 344 has a detent 345 slidably mounted in a suitable casing 346, with the end of said detent being normally urged by a coil spring 347 into locking engagement with a depression 348 in the adjacent wall of block 336.

The free end 344 of the main operating lever 323 as shown in Figs. 9 and 11, has an upstanding pin 349 thereon which mounts a roller 351 positioned between a pair of spaced parallel transverse bars 352 and 353 affixed at their ends respectively to the side bars 214 and 215 of the carriage 213 at the rear end thereof, thereby providing a channel through which the roller may move. As shown in Figs. 9 and 11, the roller 351 is eccentrically mounted on said pin 349 for slight adjustment to regulate the limits of longitudinal movement of the carriage 213 on its tracks 222, 223.

With the construction thus described, rotation of vertical shaft 315 by motor 290 in a clockwise direction as shown in Fig. 26 will first move main operating lever 323 to the right to cause the roller 351 to abut against bar 352 to move the carriage to the right. As shown in Fig. 11, this will cause the end 232 of the cradle 228 to abut against a horizontal screw 355 threaded through a depending bracket 356 affixed to the closure plate 271, and thereupon to move the latter from the position shown in Fig. 4 to the position shown in Fig. 11 to permit discharge of the bottommost bobbin 63 in each of the racks 244 onto the transversely aligned pairs of notches 234 in the cradle 228. Continued rotation of the vertical shaft 315 and the crank arm 316 will move the main operating lever 323 to the left to advance the carriage 213 and cradle 228 thereon so that the respective bobbins 63 thereon will be directly below the corresponding spindle shafts 81, 82, 83 and 84.

Means are provided to raise the cradle 228 axially to align the bobbins 63 thereon with the plurality of pairs of driving heads and bobbin presser heads. To this end, as shown in Figs. 3 and 10, a stop 361 is affixed on supporting bar 182

which desirably comprises an upstanding stud 362 in the path of movement of the front end 233 of the cradle 228. The stud 362 has a sleeve 363 eccentrically mounted thereon to permit adjustment thereof to insure that when the cradle 228 abuts thereagainst, the bobbins 63 thereon will be transversely aligned with the spindle shafts as hereinafter to be described.

Also rigidly mounted on vertical shaft 315, as shown in Figs. 26 and 30 is a cam 370 which may engage the plunger 371 of a carriage limit switch 671 affixed to track 223 as shown in Fig. 2. The cam is of such size that it will only actuate the switch 671 during a portion of the 360 degree rotation of shaft 315 and when switch 671 is actuated it will start the winding cycle of the spindle shafts in the manner hereinafter described.

Bobbin indexing cam

(Figs. 18, 19 and 22)

In order that the end thread to be wound around the bobbin 63 may be gripped by the inner ring 149 of the driving head 131 yet not by the outer ring 158, it is necessary that such thread, which is in vertical position against such driving head, be positioned as shown in Figs. 16 and 20 so as to lie in the notches adjacent diametrically opposed driving teeth 71 on the hub 65 of the bobbin 63.

To this end, means are provided to index the bobbins 63 so that a substantially diametrically spaced pair of driving teeth 71 on one of the flanges of each of the bobbins 63 in cradle 228, illustratively flange 65, will be substantially vertically aligned as shown in Fig. 20. Although the bobbin 63 may be indexed in any suitable manner, in the illustrative embodiment herein, an indexing cam 358 (Fig. 22) is provided having an arm portion 359 extending parallel to the direction of movement of the bobbin cradle 228 and lying in the path of movement of the toothed flange 65. As shown in Fig. 22, one end of the cam 358 is affixed by a set screw 360 in a block 361 adjustably mounted on one of the upright posts 258 which carry the magazine 221. A portion 362 of such cam extends obliquely inward toward the cradle from the affixed end thereof and has the arm portion 359 integral therewith.

In the operation of the bobbin indexing cam, as the cradle advances, successive toothed flanges 65 of the bobbins 63 will be moved against the arm portion 359 of the cam. This will cause the bobbins that are not already properly aligned to rotate slightly in the cradle until the arm lies, as shown in Fig. 19, across the axis of each of said bobbins and between two pairs of adjacent diametrically opposed teeth 71. Thus, all of the bobbins will have their teeth in substantially the same relative position which is such as to permit the thread to be positioned against the gripping surface 72 of the flange spaced from the axial bore in the bobbin, as shown in Fig. 20.

Means are provided to retract the rod 166 shown in Fig. 15 against the tension of the associated coil spring 203 in order to move the head 172 thereof axially away from the driving head 131 to permit positioning of a bobbin 63 therebetween. This mechanism will now be described.

Bobbin presser retracting mechanism

(Figs. 2, 8, 10, 13, 14, 26 and 28)

As shown in Figs. 8, 13 and 14, the bobbin presser retracting mechanism desirably com-

prises a shaft 365 which, as shown in Fig. 8, extends transversely between supporting bars 182 and 183 and bears in suitable bearing openings in blocks 188 and 187 respectively. Rigidly mounted on said shaft 365 between adjacent pairs of bearing blocks 181 are forks 366 and 387 respectively. The legs 368 of each fork rigidly mount a transverse rod 369, each of which is of such length that it may engage a pair of collars 208 affixed on the reduced ends 203 of the rods 166 of the associated bobbin pressers so that each rod 369 may simultaneously actuate a pair of bobbin presser heads 172.

To actuate shaft 365 in timed relation with the operating mechanism of the machine, the hub end 371 of a lever arm 372 shown in Fig. 8 is affixed to the end of shaft 365 which protrudes from block 181. As shown in Figs. 13 and 14, the free end of lever arm 372 is pivotally affixed to the free end of a release rod 374, as at 373. The other end of the release rod 374 is adjustably threaded into the end 375 of a connector link 376 shown in Figs. 26 and 27, and retained in such link by a nut 377. The connector link 376 desirably has an upstanding stud 378 therethrough as shown in Fig. 27 to which is affixed as by nut 379 the free end 382 of the arm 383 of a bell crank 384 shown in Fig. 26. The bell crank is pivotally mounted as at 385 to the rearwardly extending supporting leg 388 of casing 386 and desirably has a roller 386 on the end of the arm 387 thereof which rides against the periphery of a cam 388 rigidly affixed on vertical shaft 315 in said casing 386. A coil spring 391 retains roller 386 against cam 388 as shown in Figs. 10, 26 and 27, one end of said spring 391 being affixed to the connecting link as at 382 in Fig. 27, the other end of said spring being connected to a laterally extending stud 393 on supporting rod 183 as shown in Fig. 10, thereby normally to urge said bell crank 384 in a counter-clockwise direction as shown in Fig. 26.

A connecting rod 394 shown in Figs. 26, 27 and 28 is also associated with the release rod 374. One end of connecting rod 394 desirably extends with a sliding fit through the bore of a horizontal bearing 395 (Fig. 27) preferably formed integral with the stud 378, the connecting rod being retained in said bearing by means of nuts 396 screwed on the threaded end 397 of said rod. The free end of the connecting rod 394 is coupled by means of a conventional universal joint 398 shown in Figs. 26 and 28 to the projecting finger 399 of a lever 402 which, as shown in Figs. 26 and 28 is pivoted as at 403 on outstanding bearing blocks 404 and 405 affixed to the frame of the machine.

In order to pivot lever 402, as shown in Fig. 28, the free end thereof is pivotally connected as at 406 to one end of a pitman 401, the other end of which is pivotally connected as at 411 to the armature 412 of the end release solenoid 413 mounted on the frame, said armature 412, when the solenoid 413 is de-energized, normally being retained in its uppermost position by the tensed coil spring 414 affixed at its lower end to the lever 402 and at its other end to the frame.

In order to wind an even layer of thread on each of the bobbins 63, means are provided to guide such thread back and forth along the length of the barrel 64 of the bobbin 63 as it is being rotated. In the embodiment herein shown, the thread traverse guides 415 shown in Figs. 8, 13 and 14 are desirably provided which will now be described in detail.

Thread traverse guide

(Figs. 3, 8, 10, 13, 14 and 41)

Each of the traverse guides 415, two of which are desirably provided, each being mounted on an associated actuating rod 416 and 417, desirably comprises a base portion 418 having a longitudinal bore therethrough so that it may be slidably mounted on the associated actuating rod. Affixed to the base 418 of each of the traverse guides 415 and extending at right angles thereto is a cross bar 421, each of said cross bars, as shown in Figs. 3, 13 and 14, having an up-standing arm 422 on each end thereof, the arms desirably having substantially vertically aligned thread guides 423, 424 near the upper and lower ends thereof respectively through which the thread may pass.

As shown in Fig. 41, the upper guide 423 is desirably a reversely bent piece of wire forming a pair of parallel legs 408 and 409, one of which, i. e. leg 408 extends laterally outward from the outer face of said arm 422 being affixed thereto at one end and the free end of the other leg 409 of said wire being bent at right angles as at 410 over leg 408 to permit the insertion of the thread through the opening 410 without need for breaking such thread. The lower guide 424 is desirably conformed so that the thread may be inserted therein also without need for breaking of such thread and it is desirably provided with an opening 424' therein of size but slightly greater than the diameter of the thread to be passed therethrough.

therethrough. Desirably guide 424 comprises a length of relatively stiff resilient wire which, as shown in Fig. 41 is affixed at one end to arm 422 and extends outwardly therefrom in a plane parallel to guide 423.

423. Beyond leg 426 the wire is reversely bent as
40 at 427 to form a parallel leg 428 which extends
toward the arm 422 and is reversely bent again
as at 429 to form a loop 430 lying in a plane
substantially parallel to that of parallel legs 426
and 428. The leg 427' of the wire is then de-
45 sirable passed over legs 428 and 426 at right
angles thereto and is reversely bent as at 429'
to form a leg 430' which extends over legs 426,
428 and over loop 430.

With the construction of the guides 423 and 424 thus described, a thread may readily be positioned therein without breaking such thread. Thus, the thread is passed under leg 410 of guide 423, between legs 408 and 409 and then positioned around the end of leg 430', over the loop 430 and then under said loop. With the thread thus positioned it may readily be moved into the substantially square opening 424' formed by legs 426, 428 and legs 427' and 430' and as such opening may be made relatively small in size, not much greater than the thickness of the thread the latter will be restrained from lateral displacement in guide 424.

In order to retain the cross bar 421 of the traverse guide 415 (Fig. 3) in horizontal position, an upstanding arm 431 is formed rigid with and preferably integral with the base 418 of the traverse guide. Arm 431 desirably has a yoke conformation at the upper end thereof as shown in Fig. 3, the legs of which straddle a horizontal guide rod 432 affixed at one end to the front wall 85 of gear box 86 and at its other end to an upstanding finger 433 (Figs. 13, 14) rigid with and preferably formed integral with a bearing sleeve 434 through the bore of which the end of

the associated traverse guide actuating rod 416 or 417 extends. As shown in Figs. 13 and 14, bearing sleeve 434 desirably has a supporting leg 435 preferably formed integral therewith and desirably affixed at its lower end as at 436 to track 222. In order that the traverse guides 415 may be reciprocated by the actuating rods 416, 417 therefor when the latter are actuated in the manner hereinafter to be described, it is necessary that means be provided securely to connect the 10 traverse guides 415 to the associated actuating rod.

To this end as shown in Figs. 3, 13 and 14, each of the traverse guides 415 desirably has a hook 436 pivotally mounted thereon as at 437 preferably to the upstanding leg 431 and normally urged to downward position by a spring 438. Hook 436 is adapted to engage a block 439 affixed to a reciprocating actuating rod 416 or 417 as by set screw 442 thereby securely connecting said 15 traverse guide 415 to the block 439 so that the traverse guide may be reciprocated with said associated actuating rod.

In order that the traverse guide may be normally urged toward the block 439 so that the hook 436 may engage the latter, the block desirably has an upstanding rod 443 affixed thereto to the upper end of which one end of a coil spring 444 is affixed, the other end of said coil spring 444 being affixed as at 445 to an upstanding ledge 446 25 desirably formed rigid with the base of the traverse guide. Thus, the traverse guide will be locked by means of the coacting hook 436 and block 439 to the associated actuating rod so that upon reciprocation of the latter the traverse guides will also be reciprocated.

To reciprocate the actuating rods 415 and 417 in timed relation to the rotation of the spindle shafts, suitable driving mechanism is provided positioned in the gear box 86 shown in Figs. 29 and 31. This mechanism includes a worm 447 affixed on shaft 96 and meshing with a worm gear 448 affixed on a stud shaft 449 rotatably mounted at one end in wall 101 and extending through the rear wall 103 of the gear box 86 and through the bearing block 451 affixed thereon. Stud shaft 449 has a worm 452 affixed thereon which meshes with a worm gear 453 affixed at the end of a cam shaft 454 journalled in suitable bearing openings in upstanding walls 101, 117 and 102 respectively. Securely mounted on cam shaft 454 between upstanding walls 101 and 117 is a barrel cam 455 affixed to said cam shaft by a set screw 455'. To prevent axial displacement of said barrel cam 455, spacer collars 456 and 457 are provided, encompassing said shaft between the ends 458 and 459 of the hub 461 of the barrel cam and the adjacent upstanding walls 101 and 117. The barrel cam 455 through a suitable transmission reciprocates the actuating rods 416 and 417 which, as shown in Figs. 29 and 31 are slidably mounted in and extend through suitable aligned openings in walls 101, 117 and 102 with the forward ends of said actuating rods extending through the front wall 85 of the gear box as shown in Fig. 29 and slidably in bearing sleeves 434 as shown in Figs. 13 and 14.

The transmission between cam 455 and said actuating rods desirably comprises a pair of bell crank levers 462, each of which, as shown in Figs. 29 and 31 has a hub 463 which encompasses guide rods 124 and 125 respectively, having a sliding fit thereon. The upstanding leg 464 of each of the bell crank levers has an enlarged opening 465 therein through which extends the associated ac- 70 75

tuating rod 416 or 417, said leg being operatively connected to the associated actuating rod by means of collars 466 and 467, affixed to said rod by set screws 468. The laterally extending arm 5 469 of each of the bell cranks, as shown in Fig. 31, has a yoke conformation 471 at the end thereof, the legs of which straddle the grooved center portions 472 of collars 473 slidably mounted on spindle shafts 81 and 84 respectively.

Each of the bell crank levers is operatively connected to the barrel cam 454 by means of a roller 474 rotatably mounted on a pin 475 rigid with hub 463 and positioned in a slot 476 in the periphery of the barrel cam. With the construction thus described it is apparent that upon rotation of the barrel cam 454 shown in Fig. 29, one of the actuating rods illustratively rod 416 will be advanced while the other of the actuating rods, i. e. rod 417 will be retracted.

20 By reason of the loose fit of the actuating rods in the enlarged openings 465 in the upright legs 464 of the bell crank levers 462, and of the yoke conformations 471 at the ends of the laterally extending legs 469 of the bell crank lever, in the event that the spindle shafts 81, 84, the guide rods 124, 125 and the actuating rods 416, 417 should not be exactly parallel there is no likelihood of binding the free movement of the bell crank lever.

25 In order that the number of revolutions of the spindle shafts may be counted to regulate the number of layers of thread wound on the bobbin, as shown in Fig. 2, the stud shaft 449 extending from the rear wall 103 of the gear box 86 is operatively connected through a suitable connector 488 to a counting device 489 which, after a predetermined number of revolutions will close an associated switch 490 to stop the motor 90. As such counting device is conventional in construction, it will not be described.

30 It is to be understood that the ratio of the gearing from the main drive shaft 96 to the stud shaft 449 with respect to the ratio of the gearing from the main drive shaft 96 to the spindle shafts 81, 82, 83 and 84 may be such that every 45 revolution of the spindle shafts may be counted or any other number of revolutions may be counted as desired.

35 In order to assure a continuous supply of oil into the gear box 86 for substantially frictionless rotation of the gears therein, as shown in Fig. 2, a pump 498 is provided which is connected to a source of oil supply (not shown). Pump 498 is driven by means of a pulley 499 affixed to the end of the drive shaft 96 extending from the side wall 98 of the gear box 86, which pulley 499 is operatively connected to a pulley 500 on the pump drive shaft 501 by means of a drive belt 502.

40 Means are desirably provided to release the hook 436 from latching engagement with block 439 so that the traverse guide 415 will no longer be reciprocated by its associated actuating rod, and to lock said traverse guide 415 into inactive position so that the thread guide 424 as shown in Fig. 13 will be substantially vertically aligned with the face of the associated driving head 131.

45 To this end, as shown in Figs. 13 and 14, a pair of hook release rods 477 are provided associated respectively with each of the thread traverse guides 415. The release rods as shown, are slidably mounted in suitable bearing openings in upstanding fingers 433 and 478 rigid with the bearing sleeve 434 with the ends 479 of said release

rods protruding from the bearing opening in finger 433.

As shown in Fig. 8, the rear end of the release rods 477 are secured by set screws 481 in transverse bores 482 at the ends of a horizontal connecting rod 483.

Pivots mounted at one of their ends on the connecting rod 483 are a pair of spaced links 484 shown in Figs. 8, 13 and 14, the free ends of said links being pivotally mounted to a second connecting rod 485 parallel to connecting rod 483. Rod 485 has reduced ends 486 which extend through openings in links 484 respectively, said links 484 being retained on said ends 486 by cotter pins 487. Pivots connected at one of their ends to said connecting rods 485 is a pair of spaced levers 491 as shown in Fig. 8, the free ends of which have aligned openings therethrough accommodating a drive shaft 492 affixed thereto by set screws 493.

As shown in Figs. 8, 13 and 14, the drive shaft 492 extends parallel to drive shaft 365 and bears in suitable openings in blocks 186 and 187, extending at one end as at 494 through the block 186. A gear 495 affixed to the end of drive shaft 365 meshes with an associated gear 496 affixed on the end 494 of drive shaft 492 so that upon rotation of drive shaft 365 in clockwise direction as shown in Fig. 14, drive shaft 492 will rotate in counterclockwise direction to advance the hook release rods 477 from the position shown in Fig. 14 to that shown in Fig. 13.

During the course of such movement of the release rods the free ends 479 thereof will engage the associated upstanding finger 497 rigid with the hook 436 and pivot such hook against the tension of coil spring 438 so that it releases the associated block 439. Further movement of the release rod 477 will move the unlocked traverse guides 415 against the tension of the associated coil spring 444 along the associated actuating rods 416 or 417 respectively, to the position shown in Fig. 13 at which time the upstanding ledges 446 of the traverse guide will be engaged by suitable locking mechanism now to be described.

Traverse guide locking mechanism

(Figs. 8, 13 and 14)

As shown in the drawings, the locking mechanism desirably comprises a bail 503 which, as shown in Fig. 8, desirably has a cross piece 504 extending parallel to the front wall 85 of the gear box 86. Cross piece 504 desirably has oblique extensions 505, each with a laterally extending finger 506. The laterally extending fingers 506 extend through suitable spaced bearing blocks 507 affixed to the front wall 85 of the gear box and each of the ends of the fingers 506 has a hook 508 rigidly mounted thereon and lying in the path of the upstanding ledges 446 on the respective traverse guides 415. By means of a tensed coil spring 509 affixed at one end to the cross piece 504 of the bail 503 shown in Figs. 13 and 14 and at its other end to a supporting member 511 positioned above the cross piece 504, the hooks 508 are normally retained in the position shown in Fig. 13 in the path of movement of upstanding ledges 446 so that when the latter are moved under such hooks by the release rods 477, the hooks 508 will latch said ledges 446 to retain the traverse guides 415 in retracted position.

Means are desirably provided to insure that the same length of thread will be wound on each of the bobbins 63 and to insure stoppage of the winding action of the bobbins in the event that

any of the threads being wound thereon should break. To this end a tension control assembly is desirably provided which will now be described.

Tension control assembly

(Figs. 1, 36, 37, 38 and 39)

The tension control assembly may be mounted on top of the substantially rectangular housing 512 shown in Fig. 1 which encompasses the operating parts of the machine. Affixed on the cover 513 of said housing 512 are a pair of upstanding spaced side plates 514 and 515, each desirably having an inwardly extending socket 516 to receive the ends of a transverse rod 517 affixed in the respective sockets by means of set screws 518 as shown in Fig. 36. The rod 517 rotatably mounts an equalizing roller 519, desirably a cylindrical sleeve which is restrained from axial displacement on said rod 517 by collars 520 which flank said sleeve and are affixed to said rod as by set screws 521.

Extending transversely across said plates 514, 515 to the rear of equalizing roller 519 and in a plane parallel thereto but slightly above the latter as shown in Figs. 36 and 38, is a tension arm supporting rod 521 securely affixed at each end by set screws 522 in sockets 523 mounted on the inner face of side walls 514 and 515. Idly mounted on said rod are a plurality of elongated substantially rectangular blocks 524 preferably of metal, each having a transverse bore 525 axially therethrough to accommodate said rod 521. Each of said blocks 524 desirably has a laterally extending spacer sleeve 526 on each side thereof coaxial with and longitudinally of said rod and in abutment, thereby equally to space said blocks 524 upon said rod 521.

As shown in Fig. 38, the lower end of each of said blocks 524 has a bore 527 therethrough transversely of rod 521, each of said bores 527 receiving the end of a tension arm 528, retained in said bore as by a set screw 529.

The free end of each of the tension arms, as shown in Fig. 38 desirably mounts a roller 531 around which a length of thread may be passed. In order normally to urge the tension arms 528 toward their uppermost position as shown in Fig. 38, the upper end of each of said blocks 524 desirably has a transverse bore 532 therethrough at right angles to rod 521 and through which extends the end of an arm 533 affixed in said bore as by set screw 534 and extending outwardly therefrom. Affixed on the free end of each of said arms 533 is one end of a coil spring 535, the other end of which is anchored in a cross bar 536 near the base of the side walls 514 and 515 extending transversely thereacross and rigidly affixed thereto. In order to adjust the tension of spring 535 on each tension arm 528, the arm 533 associated therewith is threaded as at 537 and a nut 538 having an annular groove 539 in the periphery thereof as shown in Fig. 40 is threaded on each of said arms, the end of the coil spring being desirably attached to a loop of wire 541 seated in said annular groove. Thus, the tension arms are normally retained under the urging of coil springs 535 in their uppermost position as limited by a transverse trip rod 542 (Figs. 37, 38) affixed at each end as by set screws 543 in the ends of levers 544 and 545 respectively, said levers being idly mounted at their free ends on the rod 521 which extends through said levers.

By reason of the tension of the coil springs 535, the tension arms 528 will abut against trip rod 542 to pivot the levers 544 and 545 thereof in a

counterclockwise direction as shown in Fig. 39. Associated with lever 545 is a tension limit switch 546 affixed to the inner face of the side wall 515 and desirably having an upstanding operating plunger 547 with a roller 548 thereon in the path of movement of a cam conformation 549 at the end of lever 545. The cam 549 is so conformed that when levers 544 and 545 have been pivoted to a predetermined position by the upward movement of the tension arms 528 against rod 542, the cam will depress the plunger 547 to actuate the switch 546 thereby stopping the winding motor 90 in the manner hereinafter to be described.

To limit the downward movement of the tension arms 528 under the tension of the threads passed over the roller ends thereof, a bumper bail 552 is desirably provided. This bumper bail may comprise a rod which, as shown in Figs. 36 and 37, extends transversely between side walls 514 and 515 and has rearwardly bent arms 553 shown in Fig. 37, which extends through transverse bores in the lower ends of blocks 554 idly mounted on rod 521. In order to prevent sudden stoppage of the tension arms 528 when they abut against the bumper bail 552, each of the rearwardly extending arms 553 thereof has a coil spring 555 associated therewith. As shown in Figs. 36 and 38, the upper end of the coil spring 555 is desirably affixed to each of the ends of said rearwardly extending arms and the other end of the coil spring is affixed to the anchor rod 536.

Means are desirably provided to limit the pivotal movement of said bumper bail 552 by its associated coil springs 555. To this end, a pair of studs 556 is desirably affixed at one end to each of the side plates 514 and 515 respectively and extend laterally therefrom in the path of movement of the rearwardly bent ends of the bumper bail.

In order to release the tension of said tension arms 528 on the thread, means are desirably provided simultaneously to pivot all of said tension arms 528 to their lowermost position against said bumper bail 552. To this end, as shown in Fig. 37 a tension release rod 557 is provided extending transversely between said side plates 514 and 515 and rotatably mounted at one end in a socket 558 (Fig. 37) affixed to side plate 514 and rotatably mounted at its other end in a bearing 559 affixed to side plate 515, said rod 557 extending through said bearing 559. As shown in Figs. 37 and 38, a tension arm release lever 561 is associated with said release rod 557 and actuated thereby. The release lever 561 desirably comprises a bail having rearwardly bent ends 562 affixed as by set screws 563 in blocks 564.

Means are desirably provided to rotate rod 557, thereby to move the release lever 561 against the ends of the tension arms 528 to pivot the latter so that the roller ends thereof move in a downward direction as shown in Fig. 38.

To this end, a tension release solenoid 566 is provided desirably mounted on the outer face of end wall 515 adjacent the end 567 of rod 557 which extends through bearing opening 559 in said side wall 515. As shown in Figs. 37, 38 and 39, the vertical plunger 568 of said solenoid desirably has a link 569 pivoted at one end thereto, and at the other end to one end of a lever 571, affixed at its other end by a set screw 572 to the protruding end of rod 557. Thus, upon movement of the plunger 568 of solenoid 566 in upward direction as shown in Fig. 38, the rod 557 will be rotated in a clockwise direction to move the tension release lever 561 against the

tension arms 528 thereby pivoting the latter downwardly to release the tension on the threads carried thereby.

In order that tension may be maintained on the thread which is fed from suitable supply spools 573 (Figs. 1, 38) located at the back of the machine, a plurality of thread tensioning devices 574 are provided through which the thread from the spools 573 extend before passing to the tension arms 528. Each of these tensioning devices includes a pair of spaced disks 575 normally resiliently retained together and a control arm 576 over the end of which the thread passes, increased tension on said thread causing the control arm to move the tension disks apart. As such tension devices are conventional in construction and may be of the type sold by Walter Kidde & Co. of Belleville, New Jersey, and per se form no part of this invention, they will not be further described.

In order to cut the thread after it has been wound on the bobbin 63 so that the next succeeding bobbin may be wound, a thread cutting and gripping assembly is provided which will now be described.

Thread cutting and gripping assembly

(Figs. 3, 5, 6, 7, 8, 10, 12, 14, 32, 33, 34, 35 and 43)

As shown in Figs. 13, 14, 32, 33 and 35, the track 223 for the carriage 213 desirably has a plurality of U-shaped notches 577 therein aligned respectively with the spindle shafts 81, 82, 83 and 84. Mounted on said notched portion of the track 223 and extending longitudinally thereof is a substantially rectangular bar 578 which, as shown in Figs. 3, 34 and 35, is supported by means of a plurality of collars 581 through each of which extends a bolt 579, being retained on the notched portion of the tracks by means of nuts 582 as shown in Fig. 3.

Rigidly affixed to the rectangular bar 578, as shown in Figs. 32, 33, 34 and 35 is a reversely bent plate 583 preferably of metal, which has substantially U-shaped notches 584 in the reversely bent front edge 585 thereof which notches are substantially vertically aligned with the notches 577 in the track 223 immediately therebelow. As shown in Figs. 34 and 35 the rear portion 586 of the reversely bent plate 583 is conformed to define a longitudinally extending channel or track 587 in which a scissor blade operating bar 588 may be slidably mounted.

As shown in Figs. 5, 6, 7 and 10, the end 589 of scissor blade operating bar 588 which extends beyond the end of its track 587, is connected by means of link 591 to one end of a double action lever 592 shown in Figs. 5, 6, 7 and 10. Lever 592 desirably has two portions 593 and 594 pivotally mounted on a common stud 595. Lever portion 593 to which the link 591 is connected has a pair of upstanding fingers 596 and 597 along one edge 598 thereof. The other lever portion 594 which is positioned on top of portion 593 desirably has the edge 599 thereof retained against upstanding finger 597 by means of a tensed spring 831 which coacts with finger 596 and an upstanding finger 832 rigid with the upper portion 594. Thus, upon movement of the lever 592 in a counterclockwise direction, as shown in Fig. 7, the edge 599 of portion 594 will abut against upstanding finger 597 to rotate the other portion 593 and advance the link 591 and bar 588 connected thereto to the left, and upon movement of the lower portion 594 in a clockwise direction

as shown in Fig. 6, the edge 599 of member 594 will move away from finger 597 tensing the spring 831 but not moving the portion 593 of the lever 592. The double action lever 592 is normally urged to the position shown in Fig. 7 by means of a tensed coil spring 833 affixed at one end to the end 589 of bar 528 (Figs. 32, 33) and at its other end (Fig. 9) to the cross bar 834 mounted on post 835 affixed to track 223.

The scissor blade actuating bar 588 has a plurality of depending studs 836 rigidly therewith, each desirably having a reduced end which extends into an elongated slot 837 (Fig. 33) extending longitudinally of and formed in a scissor blade 838. As shown in Figs. 32 to 35 inclusive, each of the scissor blades 838 is rotatably mounted on a stud 839 which extends through a countersunk opening 841 in bar 518 (Fig. 35), through the scissor blade 842 affixed to said bar as by rivets 843 and through an opening 844 in said movable scissor blade 838 and an opening 845 in the track 223. The movable scissor blade 838 is desirably resiliently retained against the fixed scissor blade 842 as by a coil spring 846 encompassing the lower end of the stud 839 and compressed between the undersurface of the movable blade and a cross pin 847 extending through said stud.

As shown in Figs. 13, 14, 32 and 33, the fixed scissor blade 842 is so positioned that the cutting edge thereof extends forwardly of bar 578 and is substantially vertically aligned with the side edges of the U-shaped notches 584 and 577 in plate 583 and track 223 respectively.

In the embodiment herein shown, four pairs of scissor blades 838, 842 are provided and the scissor blade actuating bar 588 has four depending studs 836 coating respectively with the longitudinal slots 837 in each of the movable scissor blades 838, simultaneously to pivot the latter when the actuating bar 588 is moved in the manner hereinafter to be described.

In addition to the bar 588 actuating the movable scissor blade 838 to sever the thread, it also controls the release mechanism for the hooks 508 for the traverse guides 415. To this end, as shown in Figs. 12, 13 and 14, a tripper member is provided, desirably a stiff wire 817 idly mounted at one end on the cross piece 504 of the bail member 503 and extending through a guide loop 818 affixed to the front wall 35 of the gear box 86. The free end of the wire is desirably secured to a laterally extending stud 819 affixed to scissor blade actuating bar 588, as shown in Figs. 13 and 14. Thus, upon movement of said bar 588, the wire 817 will be pulled to pivot the hooks 508 away from the associated ledges 446 on the traverse guides 415 thereby permitting the associated coil springs 444 to slide the associated traverse guides 415 along their actuating rods 416 or 417 so that the hooks 436 may latch against the blocks 439 to permit reciprocation of said traverse guides by the associated actuating rods.

Associated with the plurality of scissor blades 838 and 842 are a plurality of thread deflector arms 848 which are clearly shown in Figs. 3, 8, 10, 35 and 42. As shown in Figs. 3 and 42, the deflector arm 848 desirably comprises a channel shaped member pivotally mounted at one end as at 849 between the plate 583 and the track 223 therebelow, the pivot 849 of said deflector arm being forwardly of the bar 578. By means of a coil spring 851 encompassing the pivot 849 of said arm 848, as shown in Fig. 42, the arm is

normally urged to the position shown in Fig. 8 in which it extends outwardly from the track 223 at substantially right angles thereto. In order to limit the outward movement of the deflector arm under the urging of the coil spring 851 associated therewith, an upstanding pin 852 is provided mounted on the track 223 and adapted to be engaged by a laterally extending conformation 853 on the pivoted end of the arm.

The deflector arm 848 desirably has two pairs of vertically aligned notches 854 and 855 in the side walls 856 and 857 thereof, each of said notches having a hook conformation 858 at the end thereof remote from the pivot 849 of said arm. The notches are so positioned along said arm, that when the latter is pivoted inwardly in the manner hereinafter to be described, a pair of vertically aligned notches will be associated with each of the pairs of scissor blades 838, 842 to move an associated thread between said scissor blades so that the thread may be severed thereby. As shown in Fig. 42, the back piece 859 of each of said deflector arms has a pair of slots 861 therein associated with each of said pair of notches to provide clearance for the movable scissor blade 832 when the latter is pivoted to sever the thread as will hereinafter be described.

Means are desirably provided to grip the threads moved between the spaced scissor blades 838, 842 by the deflector arms 848 so that such thread may dependably be severed by the blades when the movable scissor blade 838 is pivoted by the actuating rod therefor.

To this end, as shown in Figs. 3, 8, 10, 32 to 35 inclusive, a substantially rectangular frame 865, preferably of sheet metal, is provided which extends longitudinally substantially the length of plate 583 and is slidably mounted thereon as shown in Figs. 32, 33, 34 and 35. A plurality of stop bars 866, are affixed to the plate 583 extending at right angles thereto. As shown in Fig. 34 the stop bar 866 may have a thickened portion 867 with openings therethrough through which extend screws 868 and 869, said screws rigidly securing said stop bar in place, the rear end 871 of the stop bar defining an overhanging portion which overlaps the rear longitudinal bar 872 of the frame. The front portion 873 of each of the stop bars has a recess 874 therein in which is slidably mounted the front longitudinal bar 875 of the frame 865 as well as a clamp bar 876.

As shown in Figs. 32 and 33 the clamp bar 876 is operatively connected to the rectangular frame by means of a lever 877 pivoted as at 878 to the plate 583. One end 879 of the lever 877 is pivotally connected to one end of a link 882, the other end of which is pivotally connected to the clamp bar as at 883. The other end of the lever 877 is pivotally connected as at 884 to one end 60 of a link 885, the other end of which is pivotally connected as at 886 to the rear longitudinal bar 872 of frame 865. Thus, when the frame 865 is moved in one direction in the manner hereinafter described, the clamp bar 876 will be moved in the opposite direction.

As shown in Figs. 32 and 33, a plurality of clamp jaws 891 are provided pivotally mounted at one end as at 892 to the rear longitudinal bar 872 of frame 865, the front ends of said clamp jaws 891 extending forwardly of clamp bar 876. Each of the clamp jaws 891 desirably has an upstanding eye 893 through which a spring carrying rod 894 extends, said rod being affixed at its ends by set screws 895 in blocks 896 and 897 respectively, mounted on frame 865. Associated

with each of said clamp jaws 891 and encompassing rod 894 is a coil spring 898, the latter being compressed between a cross pin 899 in rod 894 and the upstanding eye 893 of the associated clamp jaw, the pivotal movement of said clamp jaw 891 by said spring 898 in a counterclockwise direction as shown in Fig. 32 being restrained by a pin 901.

Associated with each of said clamp jaws 891 and normally spaced therefrom, as shown in Fig. 32 is a short clamp jaw 903 pivotally mounted as at 904 to the clamp bar 876 and extending outwardly therefrom, at substantially right angles thereto, said clamp jaws 891 and 903 coacting with each other to grip a thread therebetween in the manner hereinafter to be described.

As shown in the Fig. 32, the clamp bar 876 is normally urged to the right by means of a tensed coil spring 904 affixed at one end to the end 905 thereof and at its other end to the cross bar 834 as shown in Fig. 9.

Actuating mechanism is provided to move the clamp arms 891 and 903 from the position shown in Fig. 32 to the position shown in Fig. 33, controlled by the movement of the main operating lever 323.

To this end, as shown in Figs. 4 and 9, a lever 906 is pivotally mounted as at 907 to a block 908 affixed to the bar 53. The upper end of said lever has an actuating rod 911 pivotally connected thereto at one end, as shown in Figs. 8, 32 and 33 extending at its other end through a block 912 that is affixed to the end of the frame 865, the extremity of said rod 911 having a collar 913 affixed thereon as by a set screw 914. The lower end of said lever 906 shown in Figs. 4 and 11 has pivotally connected thereto as at 915 a control rod 916 which extends with sliding fit through an upstanding post 917 mounted near the end of the main operating lever as shown in Figs. 4 and 9, said control rod having a collar 918 affixed to the free end thereof and being encompassed by a coil spring 919.

In addition to the clamp jaws 891 and 903 retaining the thread between the scissor blades 838 and 842, they also grip the thread so that it may be stretched taut in substantially vertical position across the face of the driving head when the tension arms 528 are released.

To accomplish the release of the tension arms, means are provided to de-energize the solenoid 566. To this end, the transverse bar 352 of the carriage as shown in Figs. 4 and 9 has a depending trip finger 920 rigid therewith which, during its movement along tracks 222, 223 strikes plunger 921 of a tension limit switch 743 mounted on angle iron 56 as shown in Fig. 10.

Bobbin disposal and storage mechanism

(Figs. 11, 21, 25, 26 and 28)

After the bobbins 63 are wound and released from the pairs of driving heads 131 and associated bobbin presser heads 132 by the movement of the latter away from the adjacent flange ends of the bobbins, the latter are transferred to a bobbin storage box 924 shown in Fig. 21.

The bobbin storage box 924 desirably comprises a substantially rectangular sheet of metal, having end walls 925 and 926 upstanding from the floor 927 thereof. The box has a plurality of longitudinal compartments 928, illustratively four in number, formed by longitudinal rods 929 transversely spaced, arranged in vertical pairs and affixed at their respective ends to the end walls 925 and 926 respectively as by means of nuts

931. End wall 925 has vertical slots 932 thereto aligned with the respective compartments 928. One end of the box, desirably that adjacent end wall 925 is provided with a plurality of spacing members 933, each of which is desirably a metal strip, bent at its upper and lower ends around the corresponding vertically aligned pair of bars 929.

The bobbin box 924, as shown in Figs. 1 and 28 10 is slidably mounted on a pair of spaced tracks which may be illustratively a pair of angle bars 935 and 936 which extend outwardly from the front of the machine at right angles to the longitudinal supporting bars 937 and 938 of the frame 51 being affixed to said supporting bars by bolts 939. The innermost position of the bobbin box 924 is limited by the abutting of a spring clip member 942 shown in Figs. 21 and 28 affixed to the side edge of the end wall 925 of the bobbin box, against a coacting spring clip 943 shown in Fig. 28, mounted on one of the upstanding legs 944 of the supporting frame for the bobbin chute 945 (Figs. 1, 3, 28). With the clip members 942, 943 engaged, the floor 927 25 of the bobbin box adjacent wall 925 will depress the plunger 339' of a bobbin box switch 940 (Fig. 28) to close said switch.

The lower end of supporting leg 944 as well as its companion supporting leg 946 is fixed respectively as by bolts 947 to the tracks or angle bars 935 and 936 and the upper ends of said legs are affixed by bolts 948 to the longitudinal supporting bar 53 of the frame as shown in Figs. 3 and 28.

35 As shown in Figs. 1 and 3, the chute 945 desirably comprises a plurality of passageways 951 illustratively four in number which decrease in width from the mouths 952 (Fig. 3) at the upper ends thereof to the outlets 953 (Fig. 28) at the lower ends thereof.

40 As shown in Fig. 28 the outlets 953 extend longitudinally of the compartments 928 in the bobbin box 924 and are of such dimensions that a bobbin 63 can pass therethrough only in substantially vertical position. The outlets 953 are vertically aligned with the rear end of the bobbin box 924 and positioned directly over an associated compartment therein so that as the bobbins 63 fall through the passageways 951 in substantially vertical position, they will be discharged from an associated outlet 953 in vertical position into the associated compartment 928 in the bobbin box between the spacers 933 thereof.

45 55 Means are desirably provided to receive the wound bobbins 63 after they have been released from the associated pairs of driving heads 131 and bobbin presser heads 132 and retain such bobbins for subsequent release into an associated passageway 951 in the chute 945. To this end as shown in Figs. 3, 24, 25, 26 and 28, a bobbin receiving hopper 954 is provided mounted beneath the frame of the machine desirably between the bars 182 and 183 as shown in Fig. 3.

60 70 As shown in Figs. 24 and 25, the hopper 954 desirably comprises a pair of spaced substantially triangular side walls 955 and 956 having upstanding ears 957 preferably formed integral therewith which are affixed to the bars 182 and 183 as by nuts and bolts 958 so as to depend from said bars. Rigid with the side walls 955 and 956 and preferably formed integral therewith is a vertical rear wall 959 and a much shorter vertical front wall 961.

As shown in Fig. 3, a plurality of spacer members 962, illustratively three in number, extend parallel to the side walls 955 and 956 and are rigidly affixed therebetween to the front and rear walls 959 and 961 of the hopper. Each spacer member desirably has a substantially wedge shaped top portion 963 positioned so as to define a plurality of compartments 964 in said hopper, vertically aligned with associated pairs of bobbin driving heads and bobbin presser heads and positioned therebelow so that when the bobbins 63 are released each will fall into an associated compartment 964. Also as shown in Fig. 3, the compartments 964 are vertically aligned with the mouths 952 of the passageways 951 in the chute 945 so that each bobbin may fall from its compartment 964 into an associated passageway.

Means are desirably provided releasably to retain the bobbin 63 in the hopper 954. To this end as shown in Figs. 3, 24, 25 and 28, a closure member 965 is provided for said compartments 964. This closure member 965 desirably comprises a substantially rectangular back plate 966 suspended desirably by a plurality of reversely bent hook conformations 967 from and slidably along the upper edge 968 of rear wall 959, as shown in Figs. 24 and 25. As shown in Figs. 3, 24, 25 the lower edge of the back plate 966 desirably has a plurality of straps 968 preferably formed integral therewith, extending obliquely upward, each with a depending lip 971 at the front edge thereof, slidably seated in a groove 972 formed by the reversely bent lower edge of the front wall 961, said straps 968 being so spaced as to close the bottom of each of the compartments 964.

In order normally to retain the straps 968 of the closure member 965 beneath the associated openings in compartments 964, a tensed coil spring 973 is provided which, as shown in Fig. 24 is affixed at one end to an eye 974 rigid with the back plate 966 and at its other end to the bar 183 as at 975.

Means are desirably provided to shift said closure member 965 against the tension of coil spring 973 so as to move the straps 968 laterally away from the mouths of the associated compartments 964 in order to open the latter.

In the embodiment herein shown, an upstanding finger 976 is affixed as shown in Figs. 3 and 25 at its lower end as by welding to the back wall 966 of the closure member 965 near the upper edge thereof. The top of finger 976 which extends above bar 182 has affixed thereto as by nuts 977, the threaded end 978 of the hopper closure member actuating rod 979.

As shown in Figs. 3 and 9, this rod 979 is substantially horizontal and the free end thereof as shown in Fig. 9 is pivotally connected as at 981 to the end of a horizontal lever 982 pivoted near its midpoint as at 983 to the longitudinal supporting bar 53. The free end of lever 982 has pivotally affixed thereto as at 984 one end of an operating rod 985 which, as shown in Figs. 4, 9 and 11 extends through the vertical leg 986 of a supporting bracket 987 which extends laterally outward from longitudinal supporting bar 53, the end of said bracket being affixed to said supporting bar as by screw 988.

In order to actuate the operating rod 985, means are provided rigid therewith and extending into the path of movement of the side bar 215 of the carriage 213 (Fig. 9). In the embodiment herein shown, a block 989 is affixed to said operating rod 985, said block having a laterally extending por-

tion 991 in the path of the end 992 of side bar 215.

Means are desirably provided intermittently to advance the stacked bobbins 63 in the bobbin box 924 so that succeeding bobbins 63 may be readily dropped therein through the chute 945. To this end as shown in Figs. 26 and 28, a pusher mechanism is desirably provided operating in timed relation with the machine and adapted intermittently to advance the stacked bobbins 63 along the compartments 928 of the bobbin box 924.

As shown, the pusher mechanism desirably comprises a plurality of bobbin pusher fingers 993 spaced sufficiently so that they may be moved into the slots 932 in the end wall of the bobbin box 924 so as to abut against the rearmost vertical bobbin 63 in each of the compartments 928 therein to advance the rows of bobbins therealong.

As shown in Fig. 28, each of the pusher fingers 993 desirably comprises a strip of metal bent into substantially rectangular shape with the ends of the strip desirably affixed to the vertical portion 994 of a horizontal angle bar 995 as by nuts and bolts 996, thereby rigidly to mount the pusher fingers on said angle bar.

The angle bar 995 is desirably affixed by screw 997 on the end of an operating bar 998 which, as shown in Figs. 26 and 28 is preferably substantially square in cross section, and is slidably mounted between and along the tracks or rails 935 and 936 for the bobbin box. A plurality of upstanding bearing straps 999 affixed by screws 1002 to cross bar 933 mount the operating bar 998 for a sliding fit.

Means are desirably provided to reciprocate the operating rod 998 in timed relation with the dropping of the bobbin 63 into the bobbin hopper 954. To this end, as shown in Figs. 26 and 28, a vertical operating shaft 1006 bears at its ends respectively in bearing blocks 1007 and 1008 which extend laterally inward from the bars 935 and 936 near the top and bottom respectively of the frame 51. Shaft 1006 which is rotatably mounted in said bearing blocks, is restrained from axial displacement through the lower bearing block 1008 by means of a collar 1009 encompassing and affixed to shaft 1006 as by set screw 1011.

Means are desirably provided to turn the shaft 1006 back and forth in timed relation with the operation of the machine. For this purpose, as shown in Figs. 26 and 28, the hub 1014 of a crank arm 1015 is drivingly connected to said shaft by means of a stiff torsion spring 1016 about the shaft, which spring is secured at one end to hub 1014 and at the other to a collar 1012 affixed upon the shaft as by a set screw 1013.

The free end of crank arm 1015, as shown in Fig. 28, desirably has an upstanding post 1017 affixed theron to the upper end of which is pivotally connected, as at 1018, one end of a connecting rod 1019, the other end of which is pivotally connected, as shown in Fig. 26, to the operating lever 323, as at 1021.

Thus, as the main operating lever 323 is operated by the drive mechanism therefor as previously described, this will in turn reciprocate connecting rod 1019 and turn the shaft 1006 back and forth.

Means are provided operatively to connect the shaft 1006 to the operating bar 998 to reciprocate the latter. To this end, a link 1022 is pivotally connected at one end to the operating bar 998, as shown in Fig. 26, with the free end of said link 1022 being pivotally connected as at 1023 to a

lever 1024. As shown in Fig. 28, the free end of lever 1024 has a hub conformation 1025 preferably formed integral therewith with a vertical bore therethrough through which said operating shaft 1006 extends, said hub being restrained from vertical displacement on shaft 1006 by means of a collar 1026 affixed to shaft 1006 immediately below said hub 1025.

To impart driving motion from the shaft 1006 to the lever 1024 thereby to actuate the operating bar 998, the hub 1025 desirably has an annular slot 1027 (Fig. 28) through a portion of its periphery extending into the bore of said hub, and a cross pin 1028 on shaft 1006 extends into said annular slot 1027. Thus, upon turning of said shaft 1006 in a clockwise direction, as shown in Fig. 26, the pin 1028 will abut against the adjacent end 1029 of the annular slot 1027 thereby to rotate the lever 1024 and through link 1022 advance the operating bar 998 to move the pusher fingers 993 into the associated slots 932 in the end wall 925 of the bobbin box 924 thereby to advance the rows of upright bobbins 63 therein.

Means are also provided to advance the operating bar 998 independently of the shaft 1006. To this end as shown in Fig. 28 a slide rod 1031 with a handle 1034 slidably extends through bearing openings in angle bars 1003 and 937 respectively, longitudinally of the side rails 935 and 936 and the rod 1031 also extends through a bearing opening in the lower portion of a depending arm 1032 rigidly affixed at its upper end to the angle bar 995 as shown in Fig. 28. A collar 1033 is affixed to rod 1031 interposed between angle bar 1003 and the lower portion of the arm 1032 so that upon pulling of the handle 1034 at the front end of rod 1031 which extends beyond the bobbin box 924, the collar 1033 will abut against arm 1032 and move the bobbin pusher fingers 993 forward in the manner previously described.

The bobbin pusher fingers 993 and the operating bar 998 therefore are returned to their rear-most position as shown in Fig. 28. In the embodiment herein shown, a collar 1035 is desirably affixed above lever 1024 to shaft 1006 as by set screw 1037. A substantially rigid return torsion spring 1038 about shaft 1006 is interposed between and affixed at its ends to collar 1035 and hub 1025.

Having thus described the component parts of the winding machine, the control circuit therefor will now be described.

Control circuit for winding machine

The control circuit diagrammatically shown in Fig. 43 may serve automatically to control the sequence of operations. This circuit comprises a main power relay 601 having a coil 602, connected at one end by lead 603 to main M2, and at its other end by leads 604 and 605 to contact 606 of the start switch 607. The other contact 608 of the start switch is connected through fuse 609 to one side of closed switch 611, the other side of which is connected to the other main M1. Desirably, an indicating lamp 612 is shunted across the coil 602 of power relay 601 to indicate when the coil 602 is energized.

The power relay 601 desirably has two pairs of normally open contacts 613, 614 and 617, 618, each having a jumper arm 619 and 622, respectively, associated therewith, said jumper arms being ganged together to move in unison when the power relay is energized. Contact 617 of the power relay 601 is connected as at 623 to leads 604 and 605 and contact 613 is connected by leads

625 and 626 to contact 608 of start switch 607. Contact 614 of power relay 601 is connected by lead 628 to contact 629 of the start switch 607, the contact 629 being normally connected to its associated contact 631 by the jumper arm 632 of said switch. The contact 631 of start switch 607 is connected by lead 633 to the contact 634 of the normally open counter switch 490 and by leads 633 and 635 to the contact 636 of the normally open manually operated trip switch 631. The contact 638 of the counter switch 490, and the contact 639 of the trip switch 637 are connected together by lead 641 which in turn is connected by lead 642 to one side of the coil 643 of relay 644, the other side of said coil being connected by lead 645 to main M2. Contact 618 of power relay 601 is connected to the contact 646 of the bobbin box switch 940. Contact 646 has an associated contact 647, said contacts being normally connected by the jumper arm 648 of said switch 940 when the bobbin box is in position to receive the wound bobbins as shown in Fig. 28. The contact 647 of the bobbin box switch 940 is connected by lead 649 to contact 651 of the tension limit switch 546 associated with the tension arms, shown in Fig. 38, the contacts 651 and 652 of said switch 546 being normally engaged by the jumper arm 653 when the tension arms are in normal operating position. The contact 652 of said switch 546 is connected by lead 654 through contacts 655 and 656 of the stop switch 657 which are normally closed or bridged by jumper arm 659, and thence by leads 659 and 626 through fuse 609 and switch 611 to main M1.

A by-pass circuit for switches 940 and 546 extends from contact 646 of switch 940 through lead 661 to the contact 662 of relay 644, the contact 663 associated with contact 662 being connected by lead 664 to contact 652 of switch 546.

The contacts 665 and 666 of the relay 644 which are normally closed by jumper arm 667 when the coil 643 of the relay 644 is de-energized, are connected respectively by lead 668 to contact 669 of the carriage limit switch 671 and by lead 672 to the contact 673 of the closed power switch 674. The movable contact arm 675' of switch 674 is connected to one side of the coil 675 of the motor relay 676, the other side of said coil being connected by lead 677 to main M2. As shown, the power relay 676 has three pairs of contacts each having an associated jumper arm 678, 679 and 681 respectively, which jumper arms are ganged together to move in unison. The contacts of relay 676 are desirably connected to a source of three-phase power P3 and to the three-phase input winding 682 of motor 90 so that upon bridging of such contacts by the jumper arms the motor 90 will be energized.

The contact 683 of the carriage limit switch 671 associated with contact 669 is normally connected thereto by jumper arm 684. Contact 683 is connected by leads 685 and 686 to the contact 614 of the main power relay 601 and also by leads 685, 687 and 688 to the contact 669 of the relay 644. In addition, contact 683 is also connected by leads 685, 687 and 688 to the contact 692 of time delay relay 693, contact 692 being normally connected to its associated contact 694 by jumper arm 695. Contact 694 is connected by lead 696 to the contact 697 of the relay 644 and to the contact 698 of the normally closed torque limit switch 297 and operating lever switch 332 which are in series and represented by a single switch 699 in Fig. 43. As shown, con-

31

tacts 698 and 701 of switch 699 are normally connected by jumper arm 702, and contact 701 is connected by lead 703 to the contact 704 of the carriage limit switch 671, the contact 705 associated with contact 704 being connected by lead 706 to contact 683 of said switch. The contact 707 of the relay 644, associated with contact 697 is connected by lead 708 to lead 642 as at 709, and contact 711 of said relay 644 is connected by leads 712 and 713 to one side of the coil 714 of the time delay relay 715, the other side of the said coil being connected by lead 716 to main M2. In addition, lead 712 is connected to contact 717 of time delay relay 715, the other contact 718 of said relay 715, which is normally disconnected from its associated contact 717 by reason of the open jumper arm 719, being connected by leads 721 and 722 to one side of the coil 723 of the relay 724 for loading motor 290 and from the other side of said coil 723 by lead 725 to main M2. In addition, contact 718 is connected by leads 721 and 726 to one side of the coil 727 of the time delay relay 693 and thence from the other side of said coil 727 by lead 728 to main M2.

Contact 711 of relay 644 is also connected by leads 712, 713 and 728 to the contact 731 of the tension release relay 732 and from contact 731 by lead 733 to the contact 734 of said relay. As shown, contact 734 is connected to its associated contact 735 by the jumper arm 736 and said contact 735 is connected by lead 737 to one side of the tension release solenoid 568, the other side of which is connected by lead 739 to main M2. Contact 731 of tension release relay 732 has an associated contact 741 normally disconnected therefrom by the spaced jumper arm 742. Contact 741 is connected by lead 743 to one side of the coil 744 of the tension release relay, the other side of which is connected by lead 745 to main M2 and contact 741 is also connected by lead 746 to the contact 747 of the normally open tension limit switch 748, the other contact 749 of which is connected by lead 751 to contact 734. As the jumper arm 752 of the tension limit switch 748 is normally spaced from contacts 747 and 749, it is apparent that such contacts will normally not be electrically connected.

The relay 724 for motor 290 has two pairs of contacts 753, 754 and 755, 756 with associated jumper arms 757 and 758, ganged together to move in unison when the coil 723 is energized and normally spaced from their associated contacts. As shown, the contact 753 is connected by leads 759, 761, 659 and 626 through fuse 609 and switch 611 to main M1 and the associated contact 754 is connected to one side of the motor 290 the other side of which is connected to contact 756, and the associated contact 755 is connected by lead 762 to main M2.

One side of the coil 763 of the latching relay 764 is connected by lead 765 to the contact 711 of the relay 644 and the other side of coil 763 is connected by leads 766 and 767 to main M2, and by leads 766 and 768 to one side of the release coil 769 for the latching arm 771, which controls the jumper arm 772 of the latching relay 764. The other side of said release coil 769 is connected by lead 773 to the contact 774 of the time delay relay 775. One of the contacts 775 of the latching relay 764 is connected by leads 777 and 772 to contact 666 of relay 644. The other contact 778 of said relay 764 is connected by leads 779 and 781 to one side of the coil 782 of time delay relay 783 and by leads 779, 75 cycle, when the start switch 607 is closed to re-

5 and 784 to contact 785 of said relay. The other side of said coil 782 is connected by lead 786 to main M2. The contact 787 associated with contact 788 is connected by lead 788 to contact 789 of said relay. As shown, the jumper arm 791 of said relay 783 is normally spaced from contacts 785 and 787. Contact 789 of time delay relay 783 is connected by lead 792 to one side of the coil 793 of time delay relay 775, the other side of said coil 793 being connected by lead 794 to main M2. The contact 789 of relay 783 is also connected to contact 795 of relay 775 and by lead 796 to contact 787. Contact 785 has an associated contact 798 normally connected thereto by jumper arm 799 which latter contact 798 is connected by lead 801 to one side of the coil 802 of the solenoid relay 803, the other side of said coil being connected by lead 804 to main M2. As shown, solenoid relay 803 has two pairs of contacts 805, 806 and 807, 808, each having an associated jumper arm 809 and 811 respectively, spaced therefrom, said jumper arms being ganged to move in unison. Contact 805 of said relay is connected by lead 812 to lead 761 as at 813, and contact 807 is connected by lead 814 to main M2. The other contacts 806 and 808 of said relay are connected respectively to the ends of the end release solenoid coil 413.

Operation

30 To facilitate understanding of the operation, a complete cycle will be described, starting with the machine at rest during the course of a winding cycle with the bobbins partially wound and 35 with the control circuit de-energized.

Referring to Fig. 43, to resume operation of the machine, the start button 607 is depressed to move the jumper arm 632 to open circuit between the contacts 629 and 631, and to close 40 circuit between contacts 609 and 669. This will complete a circuit to the coil 602 of the main power relay 601 from main M1 through closed switch 611 and fuse 609 to the closed contacts 608 and 606 of start switch 607, thence by leads 605 and 604 to one side of the coil 602 of relay 601, the other side of said coil being connected by lead 603 to main M2. Pilot light 612 connected in parallel with the coil 602 of power relay 601 will light while such coil is energized, thus indicating that power has been applied to the machine.

60 Energization of the coil 602 of power relay 601 will move the jumper arms 619 and 622 thereof into engagement with the associated pairs of contacts 613, 614 and 617, 618 to close such contacts. The closing of contacts 617, 618 of relay 601 will provide a holding circuit for the coil 602 of such relay when start switch 607 which is only closed momentarily, is released. This holding circuit is from main M1 through closed switch 611 and fuse 609, leads 620 and 659 through the normally closed contacts 656 and 655 of stop switch 657, lead 654, through the normally closed contacts 652 and 651 of tension stop switch 546 which is associated with the tension arms 523 (Fig. 38), lead 649, through the normally closed contacts 647 and 646 of the bobbin box switch 940 shown in Fig. 28, which switch is closed when the bobbin box is in position to receive wound bobbins, thence through the closed contacts 618 and 617 of power relay 601 and lead 604 to one side of the coil 602 of relay 601 and thence by lead 603 to main M2.

Inasmuch as in the middle of the winding

33

sume operation of the machine, as shown in Figs. 9 and 26, the cam 370 on the vertical shaft 315 is engaging the plunger 371 of the carriage limit switch 671, the latter will have its contacts 669 and 683 (Fig. 43) closed by jumper arm 684 and a circuit will be completed to the winding motor 99. This circuit is from main M1 through closed switch 611 and fuse 609, leads 626 and 625 through the closed contacts 613 and 614 of the power relay 601 thence by leads 688 and 685 through the closed contacts 683 and 689 of carriage limit switch 671, lead 688, through the normally closed contacts 665 and 666 of the relay 644, lead 672, through the normally closed power switch 674 to one side of the coil 675 of the winding motor relay 676, thence by lead 677 to main M2.

Energization of the coil 675 of relay 676 will move the jumper arms 678, 679 and 681 thereof against the associated pairs of contacts of said relay 676 thereby to complete a circuit from the three-phase power line P3 to the motor 99.

As shown in Figs. 2, 29 and 31, rotation of motor 98 through drive belts 94 (Fig. 2) will rotate shaft 96 and through helical gears 107, 108 affixed on said shaft will, through the meshed helical gears 112 and 113 respectively, rotate spindle shafts 81 and 84, the spur gears 118 and 119 on which, through the idler gears 122 and 123 respectively will rotate spur gears 128 and 129 to drive spindle shafts 82 and 83 in the same direction, thereby rotating the associated driving heads 131 and bobbins 63.

Simultaneously, with the rotation of the spindle shafts, the shaft 96 will by means of drive belt 502 (Fig. 2) rotate the pulley 500, which is affixed to the shaft of the oil pump 498, thereby forcing oil through the gear box 86 by means of a piping system (not shown). In addition, the rotation of shaft 96 (Fig. 29) through worm 447, drives worm gear 448, to rotate stud shaft 449 and the through the coupling 488 shown in Fig. 2, to drive the counter 489 which indicates the turns of thread as these are wound upon the bobbins.

Cam shaft 454 (Fig. 29) is also driven from shaft 96, through worm 447, worm gear 448, gear 452 and gear 453. The barrel cam 455 on shaft 454 will reciprocate actuating rods 416 and 417 for the thread traverse guides 415 (Fig. 13).

As shown in Figs. 29 and 31 the rollers 474 on the bell crank levers 462 ride in the peripheral groove 476 of the rotating barrel cam. Thus one of the actuating rods will be advanced and the other retracted and vice versa. As the bobbins are rotated, the traverse guide 415 associated with spindle shafts 81 and 82 will thus move at uniform speed in one direction and the traverse guide 415 associated with spindle shafts 83 and 84 in the opposite direction. Consequently, the thread which extends through the guides 422 and 423 (Figs. 3 and 41) will be evenly wound along the barrel of the bobbins. As the length of travel of the traverse guides 415 is substantially the same as the length of the barrel portion of the bobbin, it is apparent that the thread will be wound from the inside face of one flange of the bobbin to the inside face of its other flange. And, inasmuch as the opening 424 in the lowermost thread guide 424 is of very small dimension, substantially the same as the diameter of the thread, there will be little lateral movement of such thread in such guide as the thread is wound, thereby insuring winding in an even layer.

Each bobbin draws its thread from the corre-

34

sponding supply spool 573 (Fig. 1), one supply spool being provided to furnish thread for each of the bobbins although, if desired, a plurality of supply spools could furnish thread for each bobbin.

The operation of the tensioning means to assure that substantially the same length of thread will be wound on each of the bobbins may be briefly described as follows:

As shown in Figs. 1 and 38, the thread is drawn from a supply spool 573 through the automatically compensating tension device 574 and then passes under and around the equalizing roller 519 and over the roller 531 at the free end of the corresponding pivoted tension arm 528 to be wound around an associated bobbin 63.

In the event that one of the threads being wound should have a thickened portion there would be a tendency for such thread, as it is wound on an associated bobbin to build up more quickly, and consequently to increase the diameter of the wound layers on such bobbin at a greater rate than the diameter of the thread build up on the other bobbins. As a result, the speed at which thread is drawn onto such bobbin will be greater than that at which it is drawn onto the other bobbins. Consequently, the equalizing roller 519 which is driven by the threads passing around it, will tend to have its speed increased by thread moving at greater speed and decreased by the thread moving at lesser speed and hence will rotate at a speed which is the average of the driving speeds. As a result, the thread wound on the bobbin which is building up at greater rate will be under greater tension than threads wound on the other bobbins. This will cause the layers to build up more quickly on such first bobbin so that the diameter of the layers wound on all the bobbins will quickly tend to equalize. Inasmuch as this equalizing action occurs almost immediately as one of the bobbins tends to build up faster than the other, it is apparent that all of the bobbins will draw thread from their associated supply spools at substantially the same rate and, consequently, substantially the same length of thread will be wound on each of the bobbins.

By reason of the spring urged tension arms 528, slack in the threads is taken up so that the wind on the bobbins will not be loose and the threads will also be retained in driving engagement with the roller 519.

After a predetermined number of turns have been wound on the bobbins, the mechanical counter 489, shown in Figs. 2 and 43, will actuate the switch 490 thereof so that the jumper arm 490' of said switch will momentarily close the contacts 634 and 638.

Inasmuch as the start switch 607 is in the position shown in Fig. 43, with the jumper arm 632 thereof, closing the contacts 629 and 631 and as the contacts 613 and 614 of the energized power relay 601 are closed by jumper arm 619, a circuit will be completed to the relay 644. This circuit is from main M1 through closed switch 611 and fuse 609, leads 626 and 625 through closed contacts 613 and 614 of relay 601, lead 628 through the closed contacts 629 and 631 of start switch 607, lead 633, through closed contacts 634 and 638 of counter switch 490, leads 641 and 642 to coil 643 of the relay 644 and thence by lead 645 to main M2.

Energization of relay 644 will immediately cause the jumper arm 667 thereof to move away

from contacts 665 and 667 thereof, thereby breaking the circuit to the coil 675 of relay 674 of the winding motor 99 to open the contacts thereof, disconnecting the three-phase power line F3 from the winding motor M which will coast to a stop.

A holding circuit from the coil 643 of the relay 644 is immediately energized upon momentary closure of the counter switch 499 to maintain relay 644 energized.

This holding circuit is from main M1 through closed switch 611 and fuse 609, leads 626 and 625 through the closed contacts 613 and 614 of the power relay 601, leads 686, 687 and 681 through the contacts 692 and 694 of time delay relay 693, which contacts are normally closed by jumper arm 695, thence by lead 686 to the contacts 687 and 707 of relay 644 which contacts are closed by jumper arm 700 thereof when said relay is energized, thence by lead 708 through coil 643 of relay 644 and by lead 645 to main M2.

While said relay 644 is energized, jumper arm 700' is in engagement with contacts 689 and 711 to complete a circuit to the coil 714 of time delay relay 715. The circuit is from main M1 through closed switch 611 and fuse 609, leads 626 and 625 through the closed contacts 613 and 614 of power relay 601, leads 686, 687 and 689 through the closed contacts 689 and 711 of relay 644 and thence by leads 712 and 713 to through coil 714 of time delay relay 715 and by lead 716 to main M2.

Energization of coil 714 will cause the jumper arm 719 thereof to move into engagement with contacts 717 and 718, thereby to complete a circuit to the relay 724 for the loading motor 290. Time delay relay 715 is desirably set to close after three seconds in order to permit the winding motor 99 to coast to a stop so that the bobbins 63 will not be rotating when the loading motor 290 is energized. The circuit to loading motor 290 which is controlled by relay 715, is from main M1 through closed switch 611 and fuse 609, thence by leads 626 and 625 through the closed contacts 613 and 614 of power relay 601, leads 683, 687 689 and 711 and 688 through the closed contacts 689 and 711 of relay 644, lead 712 to the closed contacts 717 and 718 of time delay relay 715, thence by leads 721 and 722 through coil 723 of relay 724 and by lead 723 to main M2.

Energization of the coil 723 of relay 724 will move the jumper arms 757 and 758 thereof against the contacts 753, 754 and 755, 756 respectively, to complete a circuit to motor 290. The circuit is from main M1 through closed switch 611 and fuse 609, leads 626, 659, 761 and 759 through closed contacts 753, 754, thence through the load motor 290 and closed contacts 755, 756 and lead 762 to main M2.

Energization of the loading motor 290 will, through the torque limit switch 297 (Fig. 2) and reduction gears 298, drive the shaft 301 which is coupled to shaft 303. As shown in Figs. 26 and 30 rotation of shaft 303 and worm 313 thereon will, through worm gear 314, rotate vertical shaft 315. Before the loading motor begins to rotate, the roller at the end of plunger 371 of the carriage limit switch 671 rides on the periphery of cam 370 to retain the carriage limit switch 671 in the normally closed position, shown in the circuit diagram of Fig. 43. As the vertical shaft 315 is driven, cam 370 rides past said roller permitting the plunger 371 to move outwardly and thereby causing the jumper arm 684 (Fig. 43) of switch 671 to move away from contacts 689 and 683 and to engage contacts 704 and 705. Closing

of contacts 704 and 705 provides a holding circuit for the coil 643 of the relay 644. This circuit is from main M1 through closed switch 611 and fuse 609, leads 626, 625, closed contacts 613 and 614 of power relay 601, leads 686 and 685 to contact 683, thence by lead 706 to contact 705 and jumper arm 684 to contact 704 and lead 702 to the contacts 701 and 698 of switch 702 (said switch 702 representing as a single switch both the torque limit switch 297 shown in Fig. 2 and the switch 352 in series with switch 297 on the main operating lever 323 shown in Fig. 26), thence to the closed contacts 697 and 707 of relay 644, lead 681 through coil 643 of said relay by lead 681 to main M2.

By reason of the fact that it will take a short period of time for the cam 370 to move away from the roller on the plunger 371 of the carriage limit switch 671, it is apparent that the above described holding circuit will not be instantly provided as soon as loading motor 290 begins to rotate. However, by reason of the holding circuit provided through the closed contacts 682 and 684 of the time delay relay 693, the relay 644 will remain energized. The time delay relay 693 which may be set for one-half second provides sufficient time for the cam 370 to move away from the roller on plunger 371 to put the holding circuit provided by the carriage limit switch 671 into operation.

The coil 727 of the time delay relay 693 will be energized at the same time as is the coil 723 of the relay 724 controlling the loading motor 290. The circuit for the time delay relay 693 is from main M1, closed switch 611 and fuse 609, leads 626 and 625, closed contacts 613 and 614 of power relay 601, leads 686, 687 and 688, through closed contacts 689 and 711 of relay 644, lead 712, closed contacts 717 and 718 of time delay relay 715, leads 721 and 722, through coil 727 of the time delay relay 693, and thence by lead 723 to main M2. Energization of the coil of time delay relay 693 will open the contacts 682 and 684 thereof, but this will have no effect on relay 644 by reason of the holding circuit previously established by carriage limit switch 671.

As soon as the relay 644 is energized and contacts 682 and 683 thereof are closed by jumper arm 688, the switch 546 which is associated with the tension arms and the switch 643 which is controlled by the bobbin box, will be by-passed, so that between winding cycles, the bobbin box 924 may be removed for emptying, and the tension arms 528 may be manipulated without in any way affecting the operation of the machine. The by-pass circuit is from main M1 through closed switch 611 and fuse 609, leads 626 and 659 through normally closed stop switch 653, leads 654 and 664, through the closed contacts 653 and 662 of the relay 644, lead 661 through the closed contacts 613 and 617 of the power relay 601, lead 684 through the coil 602 of the power relay 601 and thence by leads 603 to main M2.

As soon as the relay 644 is energized, a circuit will be completed to the tension release solenoid 556 which is associated with the tension arms 528. The circuit for such solenoid is from main M1 through closed switch 611 and fuse 609, leads 626 and 625 through the closed contacts 613 and 614 of the power relay 601, leads 686, 687 and 688, through the closed contacts 689 and 711 of the relay 644, thence by leads 712, 713, 728 and 733 to the contacts 734 and 735 of the tension release relay 732, which contacts are normally closed by jumper arm 736, thence by lead 737 through tension release solenoid 556 and by lead 739 to main

M2. Energization of the tension release solenoid 566, as shown in Fig. 38, will cause the armature 568 of such solenoid to move upwardly, thereby pivoting the tension release lever 561 in a clockwise direction so that it will abut against the free ends of the tension arms 528, restraining the roller ends of the latter from moving upwardly under action of the coil spring 535 associated therewith.

The crank arm 316 is rotated in clockwise direction by the vertical shaft 315, as shown in Figs. 2, 9 and 26, initially to pivot the main operating lever 323 in counterclockwise direction about its pivot 324 by movement of the stud 321 at the end of the crank arm 316 away from pivot 324 15 along the elongated slot 322 of lever 323. This movement of lever 323 effects a number of functions which will now be described.

The carriage 213 shown in Figs. 4 and 9 will be moved to the right by the eccentrically mounted roller 351 on the free end of the main operating lever 323 from the position shown in Fig. 4, to bring the end 232 of the bobbin cradle 228 into engagement with the end of the horizontal screw 355 on the magazine slide 271, and in the continued movement, to shift the slide 271 to the right against the tension of coil spring 288 to the position shown in Fig. 11 in which the openings 272 in said slide register with the compartments 244 in the magazine 221 and with the bobbin supporting recesses 234 in the cradle 228. In this operation, as shown in Fig. 11, the arms 278 on the magazine slide 271 move over the bobbin being released from each compartment and under the bobbin immediately thereabove. Thus, the lowermost bobbin in each of the compartments 244 is released into the associated recesses 234 in the cradle 228, and all the bobbins thereabove are retained against discharge from compartments 244.

The movement of the carriage 213 to the right as shown in Figs. 1 and 9 will also cause the end 992 thereof to abut against the block 989 which is affixed to the actuating rod 985 for the hopper slide 965. Movement of the actuating rod 985 to the right, as shown in Fig. 9 against the resistance of coil spring 973 will pivot the lever 982 to move to the left the actuating rod 979 connected to its opposite end. This will cause the hopper slide 965 shown in Figs. 3, 24 and 25 also to move to the left, thereby moving the straps 968 thereof, which are clearly shown in Figs. 3 and 24 away from the mouths of the compartments 964 in the hopper. The wound bobbins 63 deposited in said compartments 964 during the preceding cycle of the machine, will therefore fall into the respective passageways 951 of the bobbin chute 945 to be deposited substantially vertically into the longitudinal compartments 928 in the bobbin box 924, as shown in Figs. 1 and 28.

As shown in Figs. 9 and 5, the movement of the carriage 213 to the right will also cause the end 213' thereof to move past the adjacent end of the double action lever 592. With such end of the double action lever 592 disengaged, the coil spring 833 will pull the scissor blade actuating bar 588 to the right from the position shown in Fig. 32 to that shown in Fig. 33. This movement will cause its studs 836 to pivot the movable scissor blades 838 in a clockwise direction about their pivots 839 to open them so that each of the scissors may receive a thread. The movement of the bar 588 will also cause the double action lever 592 through intervening link 591 to pivot to the position shown in dot and dash lines in Fig. 5. 70

In addition, the movement of the actuating bar 588 to the right will cause the traverse guide hooks 508 to be lowered to the position shown in Fig. 13 since the wire 817 which is connected between the bail 504 and the stud 819 on the actuating bar 588 will be slackened as that bar is moved, thereby releasing spring 509 to urge downward the bail 503 and the hooks 508 thereon.

In the continued clockwise rotation of the vertical shaft 315, shown in Fig. 26, the crank arm 316 will move the main operating lever 323 in clockwise direction about its pivot 324 resulting in a number of operations which will now be described.

As shown in Fig. 9, the end 992 of the carriage 213 will move away from the block 989 on the hopper actuating rod 985, releasing the tension on such rod so that the coil spring 973 will return the hopper closure slide 965 (Fig. 24) by movement to the right to the position shown in Fig. 3 with straps 968 of the slide 965 under the associated compartments 964 of the hopper 945 to close the mouths of such compartments for retaining bobbins to be subsequently dropped there- 25 into.

In the further rotation of the vertical shaft 315 (Fig. 26), the cam 388 moves the roller end 386 of bell crank lever 384 about its pivot 385 to move arm 383 thereof clockwise in order to pull upon the bobbin presser head release rod 374 through the connector 376 against the tension of the coil spring 391 shown in Figs. 10 and 26. Thus, release rod 374 is moved to the left, as shown in Fig. 14, thereby pivoting lever 372 and rotating shaft 385 clockwise. The clockwise rotation of shaft 385 as shown in Figs. 8, 10 and 14 will cause rods 369 mounted on the forks 366 affixed to said shaft, to press against collars 208 on the ends of the bobbin presser rods 166. As shown in Fig. 40 15, movement of each of said rods through the associated bearing 181, against the tension of the compressed coil spring 206, will retract the rotatable nose 172 thereon from the adjacent flange end 66 of the bobbin 63 to the position shown in Fig. 13 for release of the bobbin 63 which will then fall into the associated compartment 964 in the bobbin hopper 954, as shown in Fig. 3.

By reason of the configuration of the cam 388 shown in Fig. 26, the bell crank lever 384 will not be pivoted to release the bobbin presser heads 132 until after the carriage 213 has moved to the left sufficiently to permit the hopper slide 965 to close the associated compartments in the hopper so that when the bobbins are released they will be retained in said hopper 954.

The rotation of shaft 385 above described will, through the meshed spur gears 495 and 496, shown in Fig. 8, cause the shaft 492 also to rotate but in opposed direction.

Rotation of shaft 492 will, through the linkage, comprising levers 491, and links 484 advance actuating rods 477 from the position shown in Fig. 14 to that shown in Fig. 13. In this movement the free ends 479 of rods 477 will abut against hooks 436 on the traverse guides 415, first pivoting them to release the associated blocks 439 and then moving the released traverse guides 415 along actuating rods 416 or 417 until the upstanding ledge 446 at the forward end of each traverse guide, snaps under the end of the corresponding hook 508 to be engaged thereby, as shown in Fig. 13.

As the carriage moves to the left from the position shown in Fig. 2, the end 213' thereof shown in dot and dash lines in Fig. 5, will engage 75 the free end 594 of double action lever 592. How-

ever, by reason of the brake action of the lever, the lower end 594 will merely rotate about its pivot 595 to the position shown in Fig. 6 and so imparts no movement to the scissor blade actuating bar 588.

Continued movement of the main operating lever 323 in clockwise direction, as shown in Figs. 26 and 28 will cause the pitman 1019 to pivot the crank 1015 clockwise, and through torsion spring 1016 it rotates shaft 1006. This will cause the pin 1028 on said shaft 1006 (Fig. 28) to abut against the end 1029 of annular slot 1027 in the hub 1025 of lever 1024, thereby rotating lever 1024 in clockwise direction (Fig. 26). Lever 1024 through link 1022 thus advances actuating bar 998 in the direction of the arrow, shown in Figs. 26 and 28 to advance the vertical pusher fingers 26 and 28 to accommodate the openings 932 in 993 carried thereby through the bobbins 924 shown in Figs. 21 and 28, thereby pushing forward the upright bobbins in each of the longitudinal compartments to provide space therein immediately below the discharge ends of the bobbin chute 945 for accommodating the next wound bobbin.

As the main actuating lever 323 continues its clockwise movement (Fig. 26), it will advance the carriage 213 along the tracks 222 and 223 and carries the cradle 228 with the bobbins 63 transversely positioned thereon. As the carriage advances, the forward end 233 of the cradle (Fig. 8) will successively abut against the pivoted thread deflector arms 848 and then the forward end 213' (Fig. 9) of the carriage will successively abut against the deflector arms 848 to pivot the latter in clockwise direction, as shown in Fig. 8. This will cause the pair of vertically aligned notches 854 and 855 in each of said arms to engage one of the vertically hanging lengths of thread, the hooks 853 at the end of each of said notches ensuring that the threads will be positioned in each of the associated pair of vertically aligned notches. As the carriage 213 continues its motion to the left and reaches the position shown in Figs. 10 and 33, the deflector arms 848 will have been moved to extend in a plane parallel to the direction of travel of the carriage 213 and will move the lengths of thread so that each is positioned between an opened pair of scissor blades 838, 842.

By reason of the channel shaped configuration of the deflector arms 848 which straddle the pair of scissor blades 838, 842, as shown in Figs. 12, 13 and 35, the portion of the thread between the side walls 856 and 857 of the deflector arms 848 will be positively positioned between said scissor blades with no likelihood of such thread passing around the ends of said blades. As the carriage 213 advances along the tracks 222 and 223 the end wall 233 of the cradle 228, which extends beyond the front end of the carriage 213, will be arrested by abutting against the eccentrically mounted post 361 shown in Figs. 3 and 10. The eccentric post 361 is so adjusted that when the cradle abuts against it as shown in Fig. 10, its transversely aligned recesses 234 will be directly below the respective pairs of driving heads and bobbin presser heads so that the bobbins may be received thereby. As the carriage is advanced further by the main operating lever 323, its transverse rods 216, 217, by riding along the oblique faces 239 of notches 236 in the underside of the now arrested cradle will elevate the same with the empty bobbins lying therein from the position shown in Fig. 11 to that of Fig. 12, in which each bobbin is interposed between the cor-

responding driving head 131 and bobbin presser head 132 and in axial alignment therewith as shown in Fig. 10. The thread will thus be positioned between the adjacent ends of the driving head and the flange of the bobbin.

As the main actuating lever 323 reaches the end of its clockwise movement, as shown in Figs. 4 and 9, post 917 thereon slides along actuating rod 916 without imparting motion to lever 906 until said post 917 abuts against and compresses spring 918 against collar 918 on the end of rod 916. By the tension thus exerted on actuating rod 916, lever 906 is pivoted to move the upper end thereof clockwise (Fig. 4), and by tension transmitted through actuating rod 911 to slide substantially rectangular frame 865 to the right from the position shown in Fig. 32 to that in Fig. 33.

In the movement of frame 865 to the right, the clamp bar 882 connected thereto is moved to the left by the intervening transmission consisting of links 835, 877 and 882. Movement of the frame 865 to the right and the clamp bar 882 to the left will bring the pivoted clamp jaws 891 on the former and clamp jaws 893 on the latter from the position shown in Fig. 32 to the position shown in Fig. 33 in which said clamp jaws engage for clamping thread therebetween. The clamp jaws 891 being pivotally mounted upon the leg 872 of the rectangular frame 865 are normally urged in counterclockwise direction by the tensed coil springs 898, shown in Figs. 32 and 33. Hence as pivoted clamp jaws 893 are shorter than clamp jaws 891, each pair 891, 893 of jaws will pivot into edge to edge engagement when the parts are in the position shown in Fig. 33. As a result, the thread between each pair of clamp jaws will be firmly gripped regardless of whether one of the lengths of thread should be of greater diameter than the others.

With the clamp jaws 891 and 893 gripping the thread as above described, as the carriage 213 reaches substantially the end of its forward motion, its depending finger 920 (Fig. 4, 9) will engage and close the tension limit switch 748 shown in Figs. 8 and 10 and in the circuit diagram of Fig. 43.

As a result of the closing of switch 748, the tension release relay 732 shown in Fig. 43 will be energized, the circuit being from main M1 through closed switch 611 and fuse 689, leads 626 and 625, closed contacts 613 and 614 of power relay 681, leads 626, 687 and 688 through the closed contacts 689 and 711 of the relay 684, leads 712, 713, 729 and 733 through the contacts 749 and 747 of the tension limit switch 748 which are now closed by jumper arm 752, leads 746 and 743 to the coil 744 of the tension release relay 732 thence by lead 745 to main M2.

Energization of the coil 744 of the tension release relay 732 will break the circuit to the tension release solenoid 586 by moving the jumper arm 736 of relay 732 away from contacts 734 and 735. At the same time a holding circuit will be provided for the coil 744 of relay 732 so that when pin 928 releases plunger 924 by movement of the carriage 213 to the right, the tension limit switch 748 opens (Fig. 8) and the tension release solenoid 577 will remain out of circuit. This holding circuit is from main M1, closed switch 611, fuse 689, leads 626 and 625 through the closed contacts 613 and 614 of power relay 681, leads 686, 687 and 688, closed contacts 689 and 711 of relay 684, leads 712, 713 and 729, closed contacts 731 and

75 leads 712, 713 and 729, closed contacts 731 and

741 of relay 732 through coil 744 and lead 745 to main M2.

De-energization of the tension release solenoid 566 (Fig. 38) will enable the tensed coil spring 535 associated with tension arms 528 to move the ends 533 thereof against release lever 561 to pivot the latter to the position shown in Fig. 38 so that the roller ends 531 of the tension arms move upwardly.

Thus, tension will be imparted to each of the lengths of supply thread which have been previously gripped below the driving heads by the clamp jaws 891 and 903, and with the traverse guides 415 in their locked retracted position, as shown in Fig. 13, the thread carried thereby will be in substantially vertical position against the face of the driving head 131. As shown in Fig. 16, the thread when so positioned against the face of the driving head 131 will be stretched taut across such face slightly to the right of the axis thereof and across both of the faces of the outer ring 158 and inner ring 149.

Continued rotation of the vertical shaft 315, shown in Fig. 26 will cause the free end 386 of the bell crank lever 384 to move off the high point of the cam 388 thereby permitting the tensed coil spring 391 (Figs. 10, 26, 27) to pull on the connector 376 which connects actuating rod 374 for the bobbin presser heads to bell crank lever 384. This will cause the actuating rod 374 to be moved to the right in the direction of the arrow shown in Fig. 13, thereby rotating shaft 365 in counterclockwise direction and releasing the tension against the ends of rods 166. As a result, the tensed coil springs 206 associated with said rods 166, as shown in Fig. 15, will move the bobbin presser heads against the flange ends 66 of the bobbins, as shown in Figs. 10 and 15, thereby pressing each bobbin against the associated driving head 131. Simultaneously, with the rotation of shaft 365 in a counterclockwise direction, as shown in Fig. 13, shaft 492 will rotate in a clockwise direction, thereby moving the release rods 477 away from the thread traverse guides 415 and back to the position shown in Fig. 14.

The movement of the bobbins by the action of the bobbin presser heads 132 will cause the flat faces 74 of the bobbin teeth 71 to press against the face of the outer ring 158 as shown in Fig. 15, thereby moving the sleeve 152 carrying said ring 158 rearwardly on the sleeve 132, on the spindle shaft 81. Thereby the inner ring 149 is pressed against the gripping surface 72 at the end of the bobbin, securely to clamp the thread between said gripping surface and inner ring 149.

By reason of the indexing arm 359 of cam 358, the teeth 71 of the bobbin 63 will be so positioned that the thread will lie in the grooves between the diametrically opposed pair of vertically aligned teeth 71, as shown in Fig. 20, without any likelihood of such thread lying across the driving faces 74 of said teeth.

At the end of the forward movement of the carriage 213 by the main operating lever 323, the rear end 992 of the carriage will move from the position shown in Fig. 10 past the free end of the double action lever 592 to the position shown in Fig. 7, at which time the lever will straighten out under the urging of spring 831 so that the end 594 of such lever 592 will lie in the path of the return movement of the carriage. Continued rotation of the vertical shaft 315 and the crank 316 thereon will cause the main oper-

ating lever 323 again to move in a counterclockwise direction. Such movement, as shown in Fig. 7, will cause the end 992 of the carriage 213 to abut against the free end of double action lever 592 thereby pivoting said free end against finger 597 to move the other end 593 in counterclockwise direction.

This movement through the link 591 will cause the scissor blade actuating bar 588 to move to the left as shown in Fig. 33 against the tension of coil spring 833 and to pivot the movable blade 838 so that the free end thereof will move in an arcuate path through the associated slot 861 in the thread deflector arm 848 to sever such thread.

By reason of the fact that the thread is accurately positioned between the pairs of scissor blades stretched between the side wall 856 and 857 of the channel shaped deflector arm 848 and is held close to the pivot point of said scissor blades by the clamp jaws 891 and 903, there is assurance that such thread will be cut by the pair of associated scissor blades when the movable blade 838 is pivoted as above described.

Simultaneously, with the movement of the scissor blade actuating bar 588, which pivots the movable scissor blade 838 that cuts the thread, pull will be exerted on the wire 817 which is connected between the stud 819 on the scissor blade actuating bar 588 and the cross piece of the bail 504 shown in Figs. 13 and 14. The resultant pivoting of member 504 will raise the hooks 503 carried thereby so that they will no longer engage the upstanding ledges 446 at the end of the thread transverse guides 415.

As a result, the traverse guides 415 under the urging of tensed coil springs 444 will slide along the associated actuating rods 416 or 417 until the hooks 436 engage the block 439, thereby securely yet releasably locking the traverse guide 415 to the associated actuating rod to be advanced thereby.

As the carriage 213 continues its movement to the right, as above described, the free end 594 of the lever 592 will ride along the longitudinal bar 215 of the carriage being retained thereagainst as shown in Figs. 5 and 10 by the tensed coil spring 833.

As the main operating lever 323 continues its counterclockwise movement (Fig. 4), the tension of the spring 919 on actuating rod 916 will be released. As a result, the pull imparted to the post 912 (Figs. 8 and 10) on the end of the rectangular frame 865 will be discontinued. Consequently, the tensed coil spring 934 will pull on the clamp bar moving the latter in its slide 586 (Figs. 34, 35) to the right from the position shown in Fig. 33 back to the position shown in Fig. 32. As a result of such movement to the right of clamp bar 876, the rectangular frame 865 will be moved to the left through the linkage 882, 877, 885 connecting the bar to the frame. Thus, each pivoted clamp jaw 891 and each pivoted clamp jaw 903 will be moved against the intervening stop arm 866.

The rotation of the main operating lever 323 in counterclockwise direction, as above described, will also push to the left pitman 1019, thereby to turn crank 1015 counterclockwise (Fig. 26, 28) and through torsion spring 1016 to turn shaft 1006 counterclockwise.

Though torsion spring 1038, shaft 1006 turns lever 1024 in a counterclockwise direction, thereby causing the actuating bar 998 to move rearward to retract the bobbin pusher fingers 999 to afford space between the rear wall 925 of the

bobbin box 924 and the bobbins therein as shown in Fig. 28 to permit deposit of the next set of wound bobbins.

In order manually to advance the bobbins in the bobbin box 924, the operator pulls on the handle 1034 to slide the actuating bar 998 to the right until the collar 1033 thereon abuts against arm 1032, thereby to move the pusher fingers 993 into the end of the bobbin box sufficiently to provide clearance for the next set of bobbins to drop thereinto. In this movement the lever 1024 idly mounted on shaft 1006 will tense the torsion spring 1038 so that when the handle 1034 is released, that spring in its return to normal position, will pivot the lever 1024 on shaft 1006 thereby returning bar 998 and its pusher fingers 993 to their rearmost position, shown in Fig. 28.

In addition to the above described operations, as the main operating lever 323 continues its movement in counterclockwise direction, it will move the carriage 213 to the right carrying the cradle 228 along therewith, permitting the latter to slide down the transverse bars 216, 217 until it is in the normal position shown in Fig. 11.

Movement of the main operating lever 323 in counterclockwise direction will continue until the vertical shaft 315 has rotated to the position shown in Figs. 26 and 9 in which the cam 370 thereon engages the carriage limit switch 671. As a result of such engagement, as shown in Fig. 43, the jumper arm 684 will move away from contacts 704 and 705 thereby breaking the holding circuit of the coil 643 of the relay 644 and such jumper arm 684 will engage the contacts 669 and 683.

As a result of the de-energization of the relay 644, and opening of contacts 689 and 711 the circuit to the relay 724 controlling the loading motor 290 will be opened and consequently such motor will stop turning and coast to a stop in which position the roller of the carriage limit switch will rest on the cam 370 as shown in Fig. 26 near the end thereof.

The de-energization of relay 644 will also break the by-pass circuit for the stop motion switch 546 and the bobbin box switch 940, thus requiring that a bobbin box 924 be in position to close said switch 940 and that none of the threads be broken which would cause the associated tension arm 923 to open the stop motion switch 546, thereby breaking the holding circuit to the power relay 601 previously described. In addition, de-energization of the relay 644 will again move jumper arm 667 to close the contacts 665 and 666 thereof, thereby completing the circuit previously described to the relay 676 controlling the main winding motor 90 so that such motor will be connected to power main P3, to start the winding of the bobbins as previously described.

Simultaneously with the closing of contacts 665 and 666 by jumper arm 667 of the relay 644 which starts the winding motor 90, the time delay relay 783 shown in Fig. 43 will be energized. The circuit for such relay is from main M1, closed switch 611 and fuse 609, leads 626 and 625, closed contacts 613 and 614 of power relay 601, leads 628 and 625, the closed contacts 683 and 669 of the carriage limit switch 671, lead 668, closed contacts 665 and 666 of relay 644, lead 672, closed contacts 716 and 718 of the latching relay 764, lead 779 and 781 through the coil 782 of relay 783 and thence by lead 786 to main M2.

The contacts 716 and 718 of relay 764 are now closed by jumper arm 772, as the coil 763 of relay

764 had been energized by the closing of contacts 689 and 711 of relay 644 when the latter was previously energized as heretofore described. The circuit for such latching relay coil is from main M1, closed switch 611 and fuse 609, leads 626, 625 through closed contacts 613 and 614 of the power relay 601, leads 686, 687 and 688, through the closed contacts 689 and 711 of the relay 644 and thence by lead 765 through coil 763, thence by leads 766 and 767 to main M2.

Once coil 763 of the latching relay 764 is energized, the movable jumper arm 772 thereof is retained against such contacts 776 and 778 by a mechanical latch 771 even after the coil 763 is de-energized by the opening of the contacts 689 and 711 of the relay 644.

The time delay relay 783 is set for approximately two seconds to permit several layers of thread to be wound on the bobbins. At such time the jumper arm 791 of that relay 783 moves into engagement with contacts 785 and 787 thereof, thereby completing a circuit to the coil 802 of the solenoid relay 803. This circuit is from main M1, through the closed switch 611, fuse 609, leads 626, 625, closed contacts 613, 614 of power relay 601, leads 686, 685, closed contacts 683, 669 of carriage limit switch 671, lead 668, closed contacts 665 and 666 of relay 644, leads 672, 717, closed contacts 716 and 718 of relay 764, leads 779 and 784, closed contacts 785 and 787 of relay 783, lead 788, the closed contacts 785 and 793 of time delay relay 775, lead 801 to the coil 802 of the solenoid relay 803 and thence by lead 804 to main M2.

Energization of the coil 802 will move jumper arms 803 and 811 thereof across contacts 805, 803 and 801, 808 respectively, thereby completing the circuit to the end release solenoid 413 shown in Fig. 28. This circuit is from main M1 through closed switch 611 and fuse 609, leads 626, 683, 761 and 812, through the closed contacts 805 and 806 to the solenoid coil 413, thence through the closed contacts 808 and 807 and lead 814 to main M2.

Energization of the end release solenoid 413 shown in Figs. 26 and 28 will cause the armature 412 thereof to move downwardly thereof against the tension of return spring 414. The downward movement will, through link 401 pivot lever 402 thereby causing the connecting rod 394 to pull on connector member 376 and on the end release rod 374 to move the latter slightly in the direction indicated by the arrows in Fig. 14. As shown in Fig. 15, such slight movement will move the bobbin presser head away from the associated flange end 68 of the bobbin 63 about $\frac{1}{8}$ of an inch to permit the spring urged sleeve 152' to move axially to sleeve 132' which it encompasses, so that the outer ring 158 will remain against the driving teeth 71 of the bobbin. Such slight movement of ring 158 will bring it into substantially the same vertical plane as the face of the inner ring 143 to effect lateral displacement of the bobbin 63 so that the gripping surface 12 thereof is moved away from ring 149. Thus, the end of the thread normally gripped between the inner ring and the gripping surface 12 at the beginning of the winding cycle will be released. Inasmuch as driving torque will still be applied to such bobbin 63 by the outer sleeve 152 which is splined to the inner sleeve 132', the bobbin 63 will continue to rotate and the layers of thread will be able to move against the inner face of flange 65 by reason of the release of the end of the thread. After approximately two seconds which permits a few layers of thread to be wound on the bobbin, the

end release solenoid 413 is de-energized in order to permit the inner ring 149 again to be moved in driving engagement with the gripping surface 72 of the bobbin.

To this end, the time delay relay 775 shown in Fig. 43 is set for approximately two seconds and the circuit thereto is closed as soon as the end release solenoid 413 is energized. This circuit is from main M1, closed switch 611, fuse 609, leads 626, 625, closed contacts 613, 614, leads 686, 685, closed contacts 683, 669 of carriage limit switch 671, leads 668, closed contacts 665, 666 of relay 644, leads 672 and 777, closed contacts 776 and 778 of latching relay 764, leads 779, 784, closed contacts 785, 787 of relay 783, leads 788 and 792, through the coil of relay 775 and thence by lead 794 to main M2.

After approximately two seconds, the jumper arm 799 of relay 775 will move away from contacts 795 and 798 and into engagement with contacts 797 and 774 of such relay thereby breaking the circuit to said solenoid relay 803 and hence to end release solenoid 413. As a result the armature of solenoid 413 will be raised to its normal position by the coil spring 414 so that the spring urged rod 166 (Fig. 15) of the presser head may again move the bobbin laterally as heretofore described. In addition, closing of contacts 797 and 774 of relay 775 will complete a circuit to the release coil 769 of the latching relay 764. This circuit is from main M1, closed switch 611, fuse 609, leads 626, 625, through the closed contacts 613, 614 of power relay 601, leads 686, 685, through the closed contacts 683, 669 of switch 671, lead 668 through the closed contacts 665, 666 of relay 644, leads 672, 777, through the closed contacts 776, 778 of relay 764, leads 779, 784, through the closed contacts 785 and 787 of relay 783, lead 788, through lead 796 and closed contacts 797 and 774 of relay 775, lead 773 through release coil 769 and then by leads 768 and 767 to main M2.

Energization of the release coil 769 will move the latching arm 771 thereof away from the jumper arm 772 in engagement with the contacts 776 and 778 of latching relay 764 so that said arm will move to open contacts 776 and 778 thereby opening the circuit to the end release relays 783 and 775.

The mechanical latching relay above described, functions as a "memory" device that will only operate once at the beginning of each winding cycle. Thus, after a predetermined number of turns have been wound on the bobbins 63 and the counter switch 490 (Fig. 43) closes, the energization of relay 644 will close its contacts 689 and 711 to energize the latching relay 763 so that its jumper arm will close contacts 771 and 778. By reason of the mechanical latch 771, the contacts will remain closed even after relay 644 has opened at the beginning of the winding cycle. As a result, the end release of the thread by the energization of relays 783, 775 and solenoid 802 will occur.

If, during the winding of the bobbins, one of the threads being wound thereon should break, the machine will automatically come to a halt. Such safety provision is afforded by the tension arms 528 which, under the urging of the coil springs 535, shown in Fig. 36, will pivot upwardly upon release of the downward tension thereon imparted by the thread as it is being wound. Such upward movement of any of the tension arms will cause the latter to abut against the horizontal trip arm or bail 542 shown in Figs. 37, 38

and 39. As a result, the bail 542 will be lifted pivoting the levers 544 and 545 mounting the same, thereby moving the cam edge 549 of lever 544 against the roller 548 at the end of plunger 547 of the stop switch 546. Depression of the plunger will move the jumper arm 653 thereof, shown in Fig. 43 away from the contacts 651 and 652, thereby opening the circuit to the coil of the main power switch 601 to stop the operation of the machine. At such time to resume operation, the attendant need merely tie the ends of the broken thread together and pass such thread over the roller end of the tension arm 528 so that the latter is moved away from the trip rod as shown in Fig. 39 to release the pressure on the plunger of switch 546. The start button 697 may then be pressed to resume operation of the machine.

If, during the automatic operation of the machine the bobbin box 924 should fill, the movement of the pusher fingers against the rearmost bobbins in the box would slide the bobbin box forward on its supporting tracks 935 and 936 past the roller of switch 949, thereby to open the latter to break the circuit to the main power relay. As a result, automatic operation of the machine will stop and it is necessary for an attendant to remove the filled bobbin box and replace it with an empty bobbin box and then press the start button to continue the operation of the machine. The usual practice however, is to replace the bobbin boxes during the course of a doffing cycle inasmuch as at such time the switch 940 is by-passed by the circuit previously described and consequently the bobbin box which is almost full may be replaced by an empty bobbin box without any interruption in the automatic operation of the winding machine.

With the mechanical latching relay 764 provided, the contacts 776, 778 thereof will only be closed once during each winding cycle by reason of the fact that the relay 763 is only energized when relay 644 is energized after the winding cycle is completed. Thus after solenoid 413 has once been energized after the winding cycle begins, and latch release coil 709 is energized to open the contacts 776, 778 they will not again be closed until after the winding cycle is completed and the counter switch 490 closed. If not for such mechanical latching relay 764, if the machine should stop due to the stoppage of power as by the breaking of a thread which will open switch 542 or by the opening of bobbin box switch 940 if it should become full, if contacts 776, 778 should be closed each time the winding operation resumed, a circuit would again be completed to relays 783, 775 and solenoid 413. This would cause an accumulation of layers adjacent flange 65 of the bobbin and an empty spot adjacent the other flange 66 with resultant unevenness of winding.

The machine is provided with a number of safety devices to prevent any jamming that might occur from causing damage.

Thus, if a bobbin should fall in the path of the carriage 213, to stop the movement thereof, the action of the crank arm 316 against the leg 328 of the main operating lever 323 will cause such leg to rotate on its pivot 324 away from leg 327 which is pivoted at its free end to the carriage.

This will cause opening of switch 332 represented as number 702 in Fig. 43, as a result the holding circuit for the coil of relay 644 will be broken and the relay will open its contacts 689

and 711 to open the circuit to the loading motor relay, thereby de-energizing said motor. When the displaced bobbin is removed, it is a simple matter to swing the leg 327 so that it is again parallel to leg 328, and the legs 327, 328 will be so retained by the coacting detent 345 and depression 348, and resume operations by pressing the start button 607.

In addition, the torque limit switch 297 also functions in conventional manner by opening its associated switch, represented by number 699 in Fig. 3 to stop operation of the machine.

The torsion springs 1016 and 1038 shown in Fig. 28 guard against injury should a bobbin near the bobbin box block the movement of operating bar 998. The crank 1015 will, in the event of such blockage, wind the torsion springs 1016 and 1038 and not interfere with movement of the main operating lever 323.

As many changes could be made in the above construction and method, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. The method of winding a bobbin of the type having a flange end which comprises retaining the end of a thread against such flange, rotating the bobbin to wind a number of layers of thread thereon, momentarily moving the flange end of such bobbin away from the retained end of thread and completing the winding of such bobbin.

2. A machine for simultaneously winding threads on a plurality of bobbins of the type having end flanges, said machine having mechanism for the release of wound bobbins and their replacement by unwound bobbins, said mechanism comprising a plurality of pairs of bobbin driving heads and bobbin presser heads, thread gripping means on one of the heads of each of said pairs, means to position a portion of each of such threads adjacent and in front of an associated gripping means, means to apply tension to each of such threads to stretch the latter taut across the associated gripping means, means to effect axial movement of one of each pair of said heads with respect to the associated head to hold a bobbin therebetween and to effect axial displacement of such bobbins, to move a flange end of each of such bobbins against the associated gripping means to hold such taut thread, means to rotate such bobbins at substantially the same speed and for the same time to wind thread thereon, means to equalize the tension on each of such threads as it is being wound, thereby to provide substantially equal lengths of thread on each of such bobbins, means to effect relative movement between the thread gripping means and the associated end flanges while the bobbins are rotating to release the retained portions of such threads, a plurality of pairs of scissors one associated with each of said pairs of heads, and means to actuate said scissors to sever such thread.

3. The combination set forth in claim 2 in which thread deflector means are associated with each of said pairs of scissors, said deflector means being conformed to retain a section of thread between the blades of each of said pairs

of scissors at substantially right angles thereto, whereby the threads may reliably be cut when said scissors are closed.

4. A machine for simultaneously winding thread on a plurality of bobbins of the type having end flanges, said machine comprising a plurality of spindle shafts, a plurality of pairs of spaced axially aligned bobbin driving heads and bobbin presser heads, associated respectively with said spindle shafts, a bobbin magazine, means to transport a plurality of unwound bobbins from said magazine to each of said pairs of heads respectively and to position said bobbins between said pairs of heads in axial alignment therewith, thread gripping means on one of said heads of each of said pairs, means to position a portion of each of such threads adjacent and in front of an associated gripping means, means to apply tension on each of such threads to stretch the latter taut across the associated gripping means, means to effect axial movement of one of said heads of each of said pairs of heads with respect to the associated head to hold a bobbin therebetween and to effect axial displacement of such bobbins to move a flange end of each of such bobbins against the associated gripping means to hold such taut thread, means to rotate said spindle shafts at substantially the same speed and for the same time to wind the thread on the associated bobbins, means to equalize the tension on such thread as they are being wound, thereby to provide substantially equal lengths of thread on each of such bobbins, means to effect relative movement between the thread gripping means and the associated end flanges while the bobbins are rotating to release the retained portions of such threads, a plurality of pairs of scissors associated respectively with each of said pairs of heads and means to actuate said scissors to sever the thread.

5. A machine for winding threads from a thread supply onto a plurality of bobbins of the type having end flanges, said machine having mechanism for the release of wound bobbins and their replacement by unwound bobbins, said mechanism comprising a plurality of pairs of bobbin driving heads and bobbin presser heads, thread gripping means on one of the heads of each of said pairs, means to position a portion of each of such threads adjacent and in front of an associated gripping means, tension disks associated with each of said threads interposed between said gripping means and such thread supply, clamp means to grip each of such threads associated with each of said gripping means and positioned therebelow, means interposed between said gripping means and said tension disks to apply tension on each of such threads to stretch the latter taut across the associated gripping means, means to effect axial movement of one of said heads of each of said pairs of heads with respect to the associated head to hold a bobbin therebetween and to effect axial displacement of such bobbins to move a flange end of each of such bobbins against the associated gripping means to hold such taut thread, means to rotate such bobbins at substantially the same speed and for the same time to wind the thread thereon, means to equalize the tension on each of such threads as it is being wound, thereby to provide substantially equal lengths of thread on each of such bobbins, means to effect relative movement between the thread gripping means and the associated end flanges while the bobbins are rotating to release the retained portions of such threads, a plurality of pairs of scissors one associated with each of said pairs of heads

49

threads, a plurality of pairs of scissors associated respectively with each of said pairs of heads, and means to actuate said scissors to sever such threads.

6. The combination set forth in claim 5 in which said clamp means comprises a plurality of pairs of clamp jaws, one of the jaws of each of said pairs being longer than the other, said jaws being pivotally mounted at their rear ends and having their front ends substantially aligned, the jaws of each of said pairs lying in the same plane, and means are provided to move the jaws of each of said pairs toward and away from each other.

7. The combination set forth in claim 5 in which said clamp means comprises a plurality of pairs of clamp jaws, one of the jaws of each of said pairs being longer than the other, the jaws of each of said pairs lying in substantially the same plane, supporting means for said jaws, said supporting means comprising a pair of spaced parallel bars lying in substantially the same plane, the longer of said jaws being pivotally mounted at one end to one of said bars with the free ends of said jaws extending over the other of said bars and the shorter of said jaws being pivotally mounted at one end to the other of said bars, resilient means associated with said longer jaw normally pivoting the latter toward said shorter jaw and means to move the jaws of each of said pairs toward and away from each other.

8. The combination set forth in claim 5 in which said clamp means comprises a plurality of pairs of clamp jaws, one of the jaws of each of said pairs being longer than the other, the jaws of each of said pairs lying in substantially the same plane, supporting means for said jaws, said supporting means comprising a pair of spaced parallel bars lying in substantially the same plane, means slidably mounting said bars, the longer of said jaws of each of said pairs being pivotally mounted at one end to one of said bars with the free ends of said jaws extending over the other of said bars and the shorter of said jaws being pivotally mounted at one end to the other of said bars, said jaws extending substantially parallel to each other at right angles to said bars, resilient means associated with each of said longer jaws normally pivoting the latter toward said shorter jaws, and means to slide said bars in opposite direction to move said jaws toward and away from each other.

9. The combination set forth in claim 8 in which the means to slide said bars in opposite direction comprises a pair of links pivoted at one end respectively to said bars and a lever fulcrumed between its ends and pivotally connected at its opposite ends to the respective ends of said links, whereby when one of said bars is moved in one direction the other bar will move in the opposite direction.

10. As an article of manufacture, a clamp assembly comprising a plurality of pairs of clamp jaws, one of the jaws of each of said pairs being longer than the other, the jaws of each of said pairs lying in substantially the same plane, supporting means for said jaws, said supporting means comprising a pair of spaced parallel bars lying in substantially the same plane, means slidably mounting said bars, the longer of said jaws of each of said pairs being pivotally mounted at one end upon one of said bars with the free ends of said jaws extending over the other of said bars and the shorter of said jaws being pivotally mounted at one end upon the other of said bars,

50

said jaws extending substantially parallel to each other at right angles to said bars, resilient means associated with each of said longer jaws normally pivoting the latter toward said shorter jaws, a pair of links pivoted at one end respectively to said bars, a lever fulcrumed between its ends and pivotally connected at its ends to the respective ends of said links, whereby when one of said bars is moved in one direction the other bar will move in the opposite direction to move said jaws toward and away from each other.

11. A machine for winding thread on a bobbin of the type having end flanges, said machine having mechanism for the release of a wound bobbin and its replacement by an unwound bobbin, said mechanism comprising a bobbin driving head and a bobbin presser head axially aligned therewith and spaced therefrom, thread gripping means on one of said heads, means to position a portion of such thread adjacent and in front of said gripping means, means to apply tension to stretch the thread taut across said gripping means, means to effect axial movement of one of said heads with respect to the other to hold a bobbin therebetween and to effect axial displacement of such bobbin to move a flange end thereof against said gripping means to hold such taut thread, means to rotate such bobbin to wind the thread thereon, means to effect relative movement between the thread gripping means and the associated end flange while the bobbin is rotating to release the retained portion of such thread, a pair of scissors associated with said pair of heads, and means to actuate said scissors to sever such thread.

12. A machine for winding thread on a bobbin of the type having end flanges, said machine having mechanism for the release of a wound bobbin and its replacement by an unwound bobbin, said mechanism comprising a bobbin driving head and a bobbin presser head axially aligned therewith and spaced therefrom, a bobbin magazine laterally of said heads, tracks from said magazine to said heads, a carriage slidable on said tracks, a relatively movable tray on said carriage to receive an empty bobbin from said magazine, means to reciprocate said carriage between said magazine and said heads, means to elevate said tray and position the bobbin thereon between said heads when said carriage has been moved thereto, thread gripping means on one of said heads, means to position a portion of such thread adjacent and in front of said gripping means, means to apply tension on such thread to stretch the latter taut across said gripping means, means to effect axial movement of one of said heads with respect to the other to hold a bobbin therebetween and to effect axial displacement of such bobbin to move a flange end thereof against said gripping means to hold such taut thread, means to rotate such bobbin to wind the thread thereon, means to effect relative movement between the thread gripping means and the associated end flange while the bobbin is rotating to release the retained portion of such thread, a pair of scissors associated with said pair of heads, and means to actuate said scissors to sever such thread.

13. The combination set forth in claim 12 in which an operating lever is pivoted at one end to the machine and coacts at its other end with said carriage, and means to oscillate said lever about its pivot to reciprocate said carriage.

14. The combination set forth in claim 12 in which an operating lever is pivoted at one end

to the machine and coacts at its other end with said carriage, said operating lever comprising a pair of arms, one of said arms being pivoted at one end to the machine and the other of said arms being pivoted at one end to said first arm adjacent the pivoted end thereof and coacting at its other end with said carriage, releasable means associated with the free end of said first arm and the end of said second arm coacting with said carriage, to retain said arms in spaced parallel relation, said arms being conformed to define a slot therebetween when parallel to each other, and means movable along said slot to oscillate said lever on the pivot of said first arm, thereby to reciprocate said carriage.

15. The combination set forth in claim 14 in which a motor is associated with the means to oscillate said lever and a switch controlling said motor is mounted on one of the arms of said lever and controlled by the other of said arms, whereby upon pivoting of one of said arms independently of the other, said switch will be actuated to break the circuit of said motor.

16. A machine for winding thread from a thread supply onto a bobbin of the type having end flanges, said machine having mechanism for the release of a wound bobbin and its replacement by an unwound bobbin, said mechanism comprising a bobbin driving head and a bobbin presser head axially aligned therewith and spaced therefrom, thread gripping means on one of said heads, means to position a portion of such thread adjacent and in front of said gripping means, tension disks associated with said thread interposed between said gripping means and such thread supply, clamp means to grip such thread associated with said gripping means and positioned therebelow, a tension arm, means pivotally mounting said tension arm on a horizontal axis extending at right angles to the direction of travel of such thread, means at one end of said tension arm adapted to engage the thread between such clamp means and said clamp disks, resilient means associated with said tension arm normally urging the thread engaging means thereof against such thread to stretch the latter taut across the associated gripping means, means to effect axial movement of one of said heads with respect to the other to hold a bobbin therebetween and to effect axial displacement of such bobbin to move a flange end thereof against said gripping means to hold such taut thread, means to rotate such bobbin to wind the thread thereon, means to effect relative movement between the thread gripping means and the associated end flange while the bobbin is rotating to release the retained portion of such thread, a pair of scissors associated with such thread, a pair of heads, and means to actuate said scissors to sever such thread.

17. The combination set forth in claim 16 in which means are provided releasably to restrain the pivoted movement of said tension arm against such thread by said resilient means.

18. A machine for winding thread on a bobbin of the type having end flanges, said machine comprising a spindle shaft having a bobbin driving head thereon, a bobbin presser head associated with said driving head, axially aligned therewith and spaced therefrom, a bobbin magazine laterally of said heads, means to transport an unwound bobbin from said magazine to said pair of heads and to position such bobbin therebetween in axial alignment therewith, thread gripping means on said driving head, means to

position a portion of such thread adjacent and in front of said gripping means, means to apply tension on such thread to stretch the latter taut across said gripping means, means to effect axial movement of said presser head toward said driving head to hold a bobbin therebetween and to effect axial displacement of such bobbin to move a flange thereof against said gripping means to hold such taut thread, means to rotate said spindle shaft to wind thread on such bobbin, means to effect relative movement between the thread gripping means and the associated end flange while the bobbin is rotating to release the retained portion of such thread, a pair of scissors associated with said heads, means to actuate said scissors, thread deflector means associated with said pair of scissors, said deflector means being formed to retain a section of thread between the blades of said pair of scissors whereby the thread may reliably be cut when said scissors are closed.

19. The combination set forth in claim 18 in which said thread deflector means is normally spaced from such thread and means are provided to move said deflector means against such thread to position the latter between an associated pair of scissor blades.

20. The combination set forth in claim 18 in which said means to transport an unwound bobbin from said magazine to said pair of heads comprises a carriage and means to effect longitudinal movement of said carriage from said magazine to said heads, and said deflector means comprises an arm, pivoted at one end and normally extending in the path of movement of said carriage whereby when said carriage abuts against said arm it will pivot the latter to move such thread between the blades of said scissors.

21. The combination set forth in claim 18 in which said means to transport an unwound bobbin from said magazine to said pair of heads comprises a carriage and means to effect longitudinal movement of said carriage from said magazine to said heads, and said deflector means comprises a channel shaped arm pivotally mounted at one end and normally extending in the path of movement of said carriage, said arm having horizontal side walls adapted to straddle said pair of scissor blades, whereby when said carriage abuts against said arm it will pivot the latter to move the edges of said side wall against such thread to position the latter between said scissor blade at substantially right angles thereto.

22. A machine for winding thread on a bobbin of the type having end flanges, said machine comprising a bobbin driving head to rotate such bobbin and a bobbin presser head axially aligned therewith and spaced therefrom, means to effect axial movement of one of said heads with respect to the other to hold a bobbin therebetween, thread gripping means associated with one of said heads, to retain a portion of such thread against a flange of such bobbin, and means to effect relative movement between the thread gripping means and the associated end flange while the bobbin is rotating to release such retained portion of thread.

23. A machine for winding lengths of thread on a bobbin of the type having end flanges with a gripping surface thereon and an intervening barrel, said machine comprising a driven spindle shaft having a bobbin driving head thereon, a bobbin presser head spaced therefrom and axially aligned therewith, thread holding means on one

ment of one of said heads with respect to the other to grip a bobbin therebetween and to move said thread holding means against the gripping surface of the adjacent flange end of such bobbin to retain a section of the length of thread therebetween, means to rotate said spindle shaft to wind the thread on such bobbin barrel, and means to effect relative movement between said thread holding means and the associated gripping surface of the bobbin to release such retained section of thread while said spindle shaft is turning.

24. A machine for winding a length of thread on a bobbin of the type having flange ends with a gripping surface thereon and an intervening barrel, said machine comprising a driven spindle shaft having a bobbin driving head thereon, a bobbin presser head spaced therefrom and axially aligned therewith, said driving head having a thread holding portion and a bobbin driving portion coaxial therewith, said portions being relatively movable, means to effect relative axial movement of one of said heads with respect to the other to grip a bobbin between said bobbin driving portion of said driving head and said bobbin presser head and to retain a section of the length of thread between said thread holding portion and the associated gripping surface of the adjacent flange of the bobbin, means to rotate said spindle shaft to wind the thread on such bobbin barrel and means to effect relative movement between said thread holding means and the associated gripping surface of the bobbin to space the two to release such retained section of thread while said spindle shaft is turning.

25. A machine for winding a length of thread on a bobbin of the type having flange ends and an intervening barrel with one of said flanges having outstanding driving teeth spaced along the periphery of the outer face thereof defining a gripping surface on said outer face encompassed by such teeth, said machine comprising a driven spindle shaft having a bobbin driving head thereon, a bobbin presser head spaced therefrom and axially aligned therewith, said driving head having a thread holding portion adapted to coact with the gripping surface of such bobbin flange, and a bobbin driving portion adapted to coact with the driving teeth of the bobbin flange, said driving portion being coaxial with said thread holding portion and encompassing the latter, said driving portion being axially movable with respect to said holding portion, means to effect relative axial movement of one of said heads with respect to the other to grip a bobbin between said bobbin driving portion of said driving head and said bobbin presser head and to move said bobbin driving portion axially away from said thread holding portion to retain a section of the length of thread between said thread holding portion and the associated gripping surface of the flange end of the bobbin, means to rotate said spindle shaft to wind the thread on such bobbin barrel, and means to move said bobbin driving portion toward said thread gripping portion to move the gripping surface of said flange away from said thread gripping portion to release the retained section of such thread while said spindle shaft is turning and while retaining said driving portion against said driving teeth.

26. A machine for winding a length of thread on a bobbin of the type having flange ends and an intervening barrel with one of said flanges having outstanding driving teeth spaced along the periphery of the outer face thereof defining

a gripping surface on said outer face encompassed by such teeth, said machine comprising a driven spindle shaft having a bobbin driving head thereon, a bobbin presser head spaced therefrom and axially movable with respect thereto, said driving head having a thread holding portion adapted to coact with the gripping surface of such bobbin flange and a bobbin driving portion adapted to coact with the driving teeth on such bobbin flange, said driving portion being coaxial with said thread holding portion and encompassing the latter, said driving portion being axially movable with respect to said holding portion, means to effect axial movement of said presser head toward said driving head to grip a bobbin between said bobbin driving portion and said bobbin presser head and to move said bobbin driving portion axially away from said thread holding portion to retain a section of the length of thread between said thread holding portion and the gripping surface of the flange end of the bobbin, means to rotate said spindle shaft to wind the thread on such bobbin barrel, means to move the bobbin presser head away from the thread holding portion, means simultaneously to move the bobbin driving portion axially toward the thread holding portion retaining the bobbin flanges gripped between said driving portion and said presser head to move the gripping surface of such flange away from said gripping portion to release the retained section of such thread while said spindle shaft is turning and while retaining said driving portion against said driving teeth.

27. The combination set forth in claim 26 in which said thread holding portion is rigidly mounted on the end of said spindle shaft and said driving portion comprises a sleeve encompassing said thread holding portion and slidably mounted with respect thereto, said sleeve being rotatable with said spindle shaft and means are provided resiliently to urge said holding portion and said gripping portion into substantially the same plane.

28. The combination set forth in claim 26 in which said thread holding portion comprises a stud rigidly affixed at one end to said spindle shaft and having a vertical gripping face, and said driving portion comprises a sleeve encompassing said stud and splined with respect thereto, said sleeve having a vertical driving face, and resilient means are provided normally to urge said faces into substantially vertical alignment.

29. The combination set forth in claim 26 in which said spindle shaft has an axial bore in one end thereof and said holding portion comprises a stud threaded into said spindle bore and having an enlarged head portion protruding therefrom with an axial cavity therein, said stud having a vertical gripping face, a centering pin extending through the bore of said stud, having an enlarged nose positioned in the cavity in the enlarged portion of the stud, resilient means normally urging said nose beyond the vertical gripping face, a sleeve affixed to said shaft, and said driving portion comprises a sleeve encompassing said fixed sleeve and said stud and splined with respect thereto, said sleeve having a vertical driving face concentric with the gripping face, means being provided normally to urge said faces into vertical alignment.

30. In a bobbin winding machine having mechanism for the release of a wound bobbin and its replacement by an unwound bobbin, the

55

combination comprising mechanism for holding the bobbin during the winding thereof and for effecting its release when wound, means for storing wound bobbins, said means comprising a bobbin box positioned below said bobbin holding mechanism, said box having a compartment therein, a chute having its mouth in position to receive a released wound bobbin and its outlet positioned over the end of said compartment, said chute being of dimension smaller than the length of the bobbin to position the latter substantially vertically as it falls down the chute into said compartment, and means associated with the compartment to push the vertical bobbin therein forwardly to provide room for the next bobbin released into the chute.

31. In a bobbin winding machine having mechanism for the release of a wound bobbin and its replacement by an unwound bobbin, the combination comprising mechanism for holding the bobbin during the winding thereof and for effecting its release when wound, means for storing wound bobbins, said means comprising a bobbin box having a compartment therein, a substantially vertical chute having its mouth in position to receive a released wound bobbin and its outlet positioned over the end of said compartment, said chute being of dimension smaller than the length of the bobbin to position the latter in substantially vertical position in said compartment, a reciprocable pusher member associated with said bobbin box and positioned to the rear of the mouth of said chute, and means to move said pusher member into and out of said compartment, thereby to advance the bobbin previously discharged into said compartment.

32. The combination set forth in claim 31 in which a bobbin hopper is interposed between the mechanism for holding the bobbin during the winding thereof and the mouth of said chute, said bobbin hopper having a slideable closure member at the bottom thereof, means being provided to actuate said closure member to release a bobbin from said hopper into the mouth of said chute.

33. In a bobbin winding machine having mechanism for the release of a wound bobbin and its replacement by an unwound bobbin, the combination comprising mechanism for holding the bobbin during the winding thereof and for effecting its release when wound, means for storing wound bobbins, said means comprising a bobbin box having a compartment therein, a track slidably mounting said bobbin box, a discharge chute having its mouth in position to receive a released wound bobbin and its outlet positioned over the end of said compartment, said chute being of dimensions smaller than the length of the bobbin to position the latter in substantially vertical position in said compartment, means releasably to retain said bobbin box with the compartment therein beneath the outlet of said chute, a reciprocable pusher member associated with said bobbin box and positioned to the rear of the mouth of said chute, means to move said pusher member into and out of said compartment, thereby to advance the bobbin previously discharged into said compartment, and a switch associated with said bobbin box, whereby when the compartment therein is filled, the next movement of said pusher member into said compartment will move the bobbin box along its track away from the end of the chute to open said switch.

34. A machine for winding thread on a bobbin,

56

said machine comprising a gear box, a spindle shaft in said gear box and extending therefrom, a driving head on said spindle shaft, a bobbin presser head associated with said driving head axially aligned therewith and spaced therefrom, a thread guide carrier associated with said heads, an actuating rod for said carrier positioned in said gear box parallel to said spindle shaft and extending from said gear box, a guide rod in said gear box parallel to said shaft and said actuating rod, a bell crank lever in said gear box having a hub at the intersection of the legs of said crank, said hub being slidably mounted on said guide rod, one of the legs of said crank extending substantially horizontally and having a yoke on the free end thereof, a collar slidably mounted on said spindle shaft having an annular groove therein straddled by the legs of said yoke, said bell crank having a substantially vertical leg with an opening therein of greater diameter than said actuating rod which extends through said opening, means rigid with said actuating rod on each side of said vertical leg to connect said leg to said actuating rod, and means in said gear box to reciprocate said bell crank, thereby to reciprocate said actuating rod and the traverse guide.

35. As an article of manufacture, a thread guide comprising a length of wire reversely bent to form a pair of parallel legs, the leg formed by said reverse bending, being reversely bent to form a leg extending in substantially the same plane as said pair of parallel legs, said last named reversely bent leg being bent at right angles to extend over said pair of parallel legs and then reversely bent to extend in the opposite direction over said pair of parallel legs and said last named reversely bent leg.

36. A machine for winding a length of thread on a bobbin, said machine comprising means for rotating said bobbin to wind the thread thereon, a pair of horizontal scissor blades associated with such bobbin, a thread deflector arm associated with such bobbin and normally spaced from the trailing portion of the thread wound thereon, means after said bobbin is wound to move said arm against the trailing portion of thread, thereby to move a section of thread between said blades, means on said arm, straddling said blades to retain the section of the trailing portion of thread between said blades at substantially right angles thereto, and means to actuate said blades to sever the thread.

37. A machine for winding a length of thread on a bobbin, said machine comprising means for rotating such bobbin, a pair of scissor blades associated with such bobbin, a thread deflector arm associated with such bobbin and normally spaced from the trailing portion of the thread wound thereon, said arm comprising a substantially channel shaped member pivotally mounted at one end and normally extending parallel to the bobbin, the side walls of said channel extending laterally in parallel planes, means after such bobbin is wound to pivot said arm to move the edges of said side walls against the trailing portion of thread to move the latter between said blades, said side walls straddling said blades to retain a section of the trailing portion of thread between said blades at substantially right angles thereto, and means to actuate said blades to sever the thread.

38. The combination set forth in claim 37 in which said arm has a longitudinal slot in the cross piece thereof and the end of one of said

blades when actuated moves in an arcuate path through said slot.

39. The combination set forth in claim 37 in which the edges of the side walls of said arm have vertically aligned notches therein whereby when said arm is moved against such thread a portion of the latter will lie across said notches positioned between said blades.

40. The combination set forth in claim 37 in which the edges of the side walls of said arm have aligned notches therein which, at the ends thereof, remote from the pivot point of said arm, have hook conformations, whereby when said arm is pivoted against such thread said hooks will guide a portion of such thread into said notches to lie thereacross.

41. In a bobbin winding machine of the character described having means to hold a portion of a length of thread against a flange end of a bobbin prior to winding of such bobbin, a motor for rotating such bobbin, switch means for completing a circuit to said motor after such thread is held, thereby to start winding of such thread on such bobbin, means to effect relative movement between the thread holding means and the flange end of the bobbin while said bobbin is rotating to release the held portion of such thread and circuit means to energize said release.

42. In a bobbin winding machine of the character described having means to hold a portion of a length of thread against a flange end of a bobbin prior to winding of such bobbin, a motor for rotating such bobbin, switch means for closing a circuit to said motor after such thread is held, thereby to start winding of such thread on such bobbin, solenoid actuated means to release the held portion of such thread, a time delay relay having a pair of normally open contacts in series with said solenoid and a source of power, circuit means to energize said time delay relay simultaneously with the closing of the circuit to said motor, whereby after a few turns of thread have been wound on such bobbin the time delay relay will close the normally open contacts thereof to complete a circuit to said solenoid to energize the latter, thereby releasing such thread.

43. The combination set forth in claim 42 in which a counter device is controlled by a rotation of said motor and has switch means associated therewith a stop rotation of such bobbin after a predetermined number of turns have been wound thereon.

44. The combination set forth in claim 42 in which means are provided to deenergize said solenoid, said means comprising a second time delay relay having a coil in series with the normally open contacts of said first time delay relay, and having a pair of normally closed contacts in series with said solenoid and with the normally open contacts of said first time delay relay whereby when said solenoid is energized, said second time delay relay will be energized to open the normally closed contacts thereof, thereby breaking the circuit to said solenoid.

45. In a bobbin winding machine of the character described having means to hold a portion of a length of thread against a flange end of a bobbin prior to winding of such bobbin, a motor for rotating such bobbin, switch means for closing a circuit to said motor after such thread is held thereby to start winding of such thread on such bobbin, solenoid actuated means to release the held portion of such thread, a latching relay having a pair of contacts and a jumper arm for

said contacts, circuit means to energize said relay to move said jumper arm against said contacts to close the latter, a latch associated with said jumper arm to retain the latter against said contacts after said relay is deenergized, a time delay relay having a coil in series with said pair of contacts and a source of current, means to complete a circuit through said pair of contacts and said coil simultaneously with the energization of said motor, said time delay relay having a pair of normally open contacts in series with the contacts of said latching relay, a source of current and said solenoid, whereby after a few turns of thread have been wound on such bobbin, the time delay relay will close the normally open contacts thereof to complete a circuit to said solenoid to energize the latter, thereby releasing such thread.

46. The combination set forth in claim 45 in which a second time delay relay is provided having a coil in series with the normally open contacts of said first time delay relay and a source of current, said second relay having a pair of normally open contacts and a pair of normally closed contacts in series with said solenoid, the normally open contacts of said first time delay relay and the pair of contacts of said latching relay, and said latching relay has a coil controlling said latch and in series with the pair of normally open contacts of said second time delay relay and the source of current, whereby when said first time delay relay is energized to energize said solenoid, the coil of said second time delay relay will be energized, to open the normally closed contacts thereof, thereby to break the circuit to the solenoid to de-energize the latter and to close the normally open contacts of said second time delay relay to complete a circuit to the coil of said latching relay, thereby to move said latch from the jumper arm of said relay to open the contacts thereof to break the circuit to said time delay relays and said solenoid.

47. In a bobbin winding machine of the character described comprising a spindle shaft, mechanism associated with said spindle shaft for holding a bobbin thereon, and releasing such bobbin after it is wound, a bobbin magazine and conveyor means for transporting an empty bobbin to said mechanism, a winding motor for driving said spindle shaft, a counter device controlled by said motor having a switch, a relay controlled by said counter switch, said relay having a pair of normally closed contacts and a pair of normally open contacts, said normally closed contacts being in series with said motor and a source of current, whereby after a predetermined number of revolutions of said motor, said counter switch will energize the relay to open the circuit to said winding motor, a loading motor associated with said conveyor means, controlled by said pair of normally open contacts, said loading motor being energized after said relay is energized to move an empty bobbin to said holding means and to release the wound bobbin, and switch means controlled by the rotation of said loading motor to break the circuit to said relay to open the circuit to said loading motor and close the circuit to said winding motor.

48. The combination set forth in claim 47 in which said counter switch is only momentary acting and a holding circuit is provided for said relay, closed when said counter switch closes.

49. The combination set forth in claim 47 in which said counter switch is only momentary act-

ing and a first holding circuit is provided for said relay, closed when said counter switch is closed and a second holding circuit is provided for said relay closed after said loading motor has been energized, said second holding circuit including said switch means controlled by the rotation of said loading motor.

50. The combination set forth in claim 47 in which said counter switch is only momentary acting and a first holding circuit is provided for said relay closed when said counter switch is closed and a second holding circuit is provided for said relay closed after said loading motor has been energized, said second holding circuit including said switch means controlled by the rotation of said loading motor, said first holding circuit including a time delay relay having a pair of normally closed contacts in series with said first holding circuit, said time delay relay being energized simultaneously with the energization of said loading motor.

51. The combination set forth in claim 47 in which a time delay relay having a pair of normally open contacts is associated with said loading motor, said relay being controlled by the normally open contacts of the relay associated with said counter switch whereby, when said last named contacts are closed, said time delay relay will function to close its contacts after said winding motor has coasted to a stop.

52. In a bobbin winding machine of the character described comprising a start switch having a pair of normally open contacts, a power relay having a coil in series with said open contacts of said start switch and a source of current, whereby when said start switch is pressed, said relay coil will be energized, said power relay having a pair of normally open contacts, closed when said relay is energized, a winding motor, a relay having a pair of normally open contacts and a pair of normally closed contacts, said closed contacts being in series with said winding motor, said pair of normally open contacts of said power relay and a source of current, whereby when said start button is pressed said winding motor will be energized, a counter switch controlled by said winding motor, said relay having a coil in series with said counter switch and a source of current, whereby after a predetermined number of revolutions of said winding motor said counter switch will close the circuit to said relay, opening the normally closed contacts thereof and closing the normally open contacts thereof, a loading motor controlled by said last named normally open contacts whereby upon closing thereof, said loading motor will be energized, and upon opening of the

normally closed contacts thereof, the winding motor will be de-energized.

53. In a bobbin winding machine of the character described, comprising a momentary start switch having a pair of normally open contacts and a pair of normally closed contacts, a power relay having a coil in series with said normally open contacts of said start switch and a source of current, whereby when said start switch is pressed, said relay coil will be energized, said power relay having a pair of normally open contacts in series with the normally closed contacts of said start switch and the source of current, a winding motor, a relay having a pair of normally open contacts and a pair of normally closed contacts, said closed contacts being in series with said winding motor, said pair of normally open contacts of said power relay and a source of current, whereby when said start button is pressed, said winding motor will be energized, a counter switch controlled by said winding motor, said switch being in series with the normally closed contacts of said start switch, the coil of said relay and a source of current, whereby after a predetermined number of revolutions of said winding motor, said counter switch will close the circuit to the coil of said relay, opening the normally closed contacts thereof and closing the normally open contacts thereof, a loading motor controlled by said last named normally open contacts whereby upon closing thereof, said loading motor will be energized, and upon opening of the normally closed contacts thereof, the winding motor will be de-energized.
